UNITED STATES PATENT OFFICE.

JOHN CHRISTER ENBERG, OF SKÄRSÄTRA, SWEDEN.

CALCULATING-MACHINE.

1,341,049.

Specification of Letters Patent.

Patented May 25, 1920.

Application filed August 20, 1914. Serial No. 857,702.

To all whom it may concern:

Be it known that I, JOHN CHRISTER ENBERG, a subject of the King of Sweden, and resident of Villa Önskebo, Skärsätra, in the 5 Kingdom of Sweden, have invented certain new and useful Improvements in Calculating-Machines, of which the following is a specification, reference being had therein to the accompanying drawings.

Calculating machines are already known which are specially designed for easy carrying out of multiplication and division, on which multiplication and division as well as addition and subtraction can be performed 15 with them merely by one movement of a handle or lever for each digit in the multiplier or divisor. The work is extremely simple in these machines.

A machine of this kind is known as the 20 "millionaire", and is described in the United States Patent No. 538710 to Otto Steiger. This machine, however, which otherwise fulfills the highest requirements, has the disadvantage of being too large to be placed 25 upon an ordinary writing table, of being noisy in use, and of complication and waste of time in setting up or registering the numbers in the machine as well as in changing 30 from one method of calculation to another.

All calculating processes can be reduced to elementary operations of addition or subtraction, and in all machines except the above-named "millionaire", the numbers used in carrying out these elementary operations are the ordinary digits 1-9, whereas in the "millionaire" machine use is made 35 of an artifice first made known in Napier's bones (see Cantor, *Geschichte der Mathematik* Vol. II, page 723), according to which 40 all the products of the digits 1-9 are divided into tens and units (for example $3 \times 9 = 2$ tens + 7 units).

Thus the "millionaire" machine comprises 45 a series of calculating elements corresponding to the products 1-81 expressed in the terms just stated, so that it may be said that a series of multiplication tables are "stored up" in the machine. By means of this great number of stored up terms the

advantage is gained that a multiplication 50 can be brought about by a simple process of addition of partial products, or, in other words, that only one revolution of the crank is required in multiplying by any of the digits, two revolutions when multiplying 55 with a number consisting of two digits, and so on. It is to machines of this kind capable of performing addition, subtraction, multiplication and division, that the present invention relates. 60

According to the present invention, the calculators (the operative members of which are gear teeth or the like) are associated in pairs, one calculator of a pair having teeth representing the tens digit and the other 65 having teeth representing the units digit, of a partial product (1-81) and the number and direction of operation (positive or negative) of the teeth being such that when the units digit of a partial product exceeds five, 70 the number of the tens teeth is one in excess of the tens digit of the product while the units teeth are of opposite (negative) operation and complementary in number to the units digit in question, whereas when 75 the unit digit of a partial product is five or less both tens and units teeth of a corresponding pair of calculators are equivalent in numbers to the digits of the product and operate in the same direction (positively) in 80 the ordinary way.

The positive and negative operations of the teeth can be obtained by using oblique teeth of two opposite inclinations so that gears operated by the calculators will be 85 turned in one direction by "positively" inclined teeth and in the other by "negatively" inclined teeth, assuming of course that the movement of the calculators is similar in the two cases. 90

This arrangement leads to increased simplicity in the machine according to the invention. In the example given above, viz, $3 \times 9 = 2$ tens + 7 units, the work in the known machine is performed by $2+7=9$ 95 teeth or like working members on the calculators. In the present machine the change is made that the product is stated in figures

which occasion less work in the machine, viz. $3 \times 9 = 27$ tens—3 units, so that the work in the machine is performed by $3+3=6$ teeth (instead of 9 working members in the previous case) and not only can the work in the machine be reduced, but also the space occupied by the calculators which "store up" the products is considerably lessened, which contributes to make the machine relatively small and considerably smaller than the "millionaire" machine, from the actual construction of which moreover the present machine entirely differs.

In general, the machine according to the present invention, while possessing the advantages of the "millionaire" machine, is at the same time free from the disadvantages of the latter, being so small that it can without inconvenience be stood on a writing table, working comparatively quietly, having a simple arrangement for setting up or registering the numbers in the machine, and rendering the work of multiplication and division still simpler than with the "mil-

lionaire", whereby calculations can be made 25 with remarkable rapidity and ease.

In machines which perform multiplication by repeated addition, it has been proposed, in multiplying for example by 17, to multiply the multiplicand first by twenty, 30 then by three, the complement of the units digit of the multiplier, and to subtract the latter from the former product, the machine being adapted to operate automatically according to this general principle, 35 but in these machines all calculations are performed by the digits themselves whereas in the machine according to the present invention all calculations, even additions and subtractions, are performed with the aid of 40 the simplified system of partial products according to Napier as outlined above.

Following is given a reconstructed multiplication table which is the basis of the present machine construction, and in which 45 tens are denoted by Roman figures and the units by Arabic.

	Times 1.	Times 2.	Times 3.	Times 4.	Times 5.	Times 6.	Times 7.	Times 8.	Times 9.
1	1=0+1	2=0+2	3=0+3	4=0+4	5=0+5	6=I-4	7=I-3	8=I-2	9=I-1
2	2=0+2	4=0+4	6=I-4	8=I-2	10=I	12=I+2	14=I+4	16=II-4	18=II-2
3	3=0+3	6=I-4	9=I-1	12=I+2	15=I+5	18=II-2	21=II+1	24=II+4	27=III-3
4	4=0+4	8=I-2	12=I+2	16=II-4	20=II	24=II+4	28=III-2	32=III+2	36=IV-4
5	5=0+5	10=I	15=I+5	20=II	25=II+5	30=III	35=III+5	40=IV	45=IV+5
6	6=I-4	12=I+2	18=II-2	24=II+4	30=III	36=IV-4	42=IV+2	48=V-2	54=V+4
7	7=I-3	14=I+4	21=II+1	28=III-2	35=III+5	42=IV+2	49=V-1	56=V+6	63=VI+3
8	8=I-2	16=II-4	24=II+4	32=III+2	40=IV	48=V-2	56=V+6	64=VI+4	72=VII+2
9	9=I-1	18=II-2	27=III-3	36=IV-4	45=IV+5	54=V+4	63=VI+3	72=VII+2	81=VIII+1

In the above table 56 is for constructional reasons expressed by $V+6$ instead of $VI-4$, 50 there being insufficient room for six teeth at the place where this calculator is situated, while six teeth can readily be placed on the corresponding unit calculator.

According to one form of the present invention, the calculators embodying the 81 different partial products are built up into a cylinder or drum, the circumference of which is formed of segment-shaped calculators. The calculator element may however have other forms, for which reason the invention comprises any calculating mechanism in which the co-operating calculators can in positive calculation carry out either two positive operations or a positive and a negative operation for forming a product, when the unit figure exceeds 5.

The invention also comprises a number of detail constructions, the nature of which will be clear from the following description of the apparatus in its entirety.

A calculating machine according to the present invention is illustrated on the accompanying drawings, wherein when a series of similar mechanisms occur some are omitted so that the parts lying behind or

under them may be visible, as are also various parts, such as gears and shafts for the sake of clearness.

Figures 1 and 1^a are front elevations of the machine, parts of the casing being 80 omitted in order to show the parts behind.

Fig. 2 shows an end elevation of the machine, seen from the left side in Fig. 1, the side frame of the machine and some other parts being omitted.

Fig. 3 shows a calculating ring, with calculators, arms, and shafts belonging to same, seen in end elevation with some parts in section.

Fig. 4 shows in section along the line 4—4 90 of Fig. 5, one of the parts (called calculators in the following,) which make up a calculating ring.

Fig. 5 is a section along the line 5—5 of Fig. 4.

Fig. 6 shows a calculating ring of modified construction.

Fig. 7 shows a development of a calculating ring.

Fig. 8 shows a detail indicating the position of the quotient registering-wheels in relation to the adjacent parts.

Figs. 9-11 show cam and groove disks

which serve to perform certain movements in the different parts of the machine during the course of calculating operations, Fig. 9 showing such a disk with the grooves and 5 tracks formed in it, Fig. 9^a a section through a disk, Fig. 10 a vertical section through the disks fixed on one end of the drum shafts, and Fig. 11 one of these disks.

5 Figs. 12 and 12^a show brake-wheels for 10 shafts journaled in the machine.

Figs. 13 and 13^a show details of the result and quotient registering-wheels.

Figs. 14-17 show in different positions 15 details of the arrangement for transfer or "carrying."

Figs. 18 and 19 show in two different positions figure-sectors on which the numbers recorded or set up on the key-board can be read off.

20 Figs. 20-28 show details in the printing mechanism of the calculating machine.

Figs. 29 and 30 show in two different positions the keys by which the numbers are set up.

25 Fig. 31 shows a section along the line 31-31 in Fig. 30, seen from above.

Fig. 32 shows a detail of the arrangement for indicating the sign for the kind of calculation for which the machine is set.

30 Fig. 33 shows type-wheels and other details of the printing mechanism.

Fig. 33^a is a plan view of mechanism shown in Fig. 33.

35 Figs. 34-37^a show details of the key arrangement for setting up the figures in multiplication.

Figs. 38-39 show a modification of the carrying device of the carriage.

40 Fig. 40 shows a transverse section through the carriage.

Fig. 41 is a longitudinal section through the end part of a cylinder of the carriage.

Fig. 42 shows in detail an arrangement for imparting motion to said cylinder.

45 Fig. 43 is an approximate plan partly in section showing the relation between the registering wheels and the transmitting wheels.

Figs. 44^a and 44^b show side elevations 50 partly in section of details of a part of the carrying mechanism.

Figs. 45 and 46 are transverse sectional views showing two different positions of other carrying mechanism elements.

55 Fig. 47 is an edge view of a disk for controlling alinement of type.

This machine consists of seven principal parts, namely:

(1) Recording mechanism.

60 (2) Calculating mechanism.

(3) The carriage.

(4) Mechanism for performing movement of and in the carriage.

(5) Mechanism for setting the machine for desired kind of calculation. 65

(6) Mechanism for indicating the kind of calculation, for which the machine is set.

(7) The printing mechanism.

The machine is provided with a frame 1, comprising both side and dividing members 70 and a top, a casing 2, and a base plate 3, by which the mechanism is supported.

(1) RECORDING MECHANISM.

The recording or setting up of a number 75 in the machine takes place by pressing down the numeral keys 4 (Figs. 1, 2, 29 and 30). The keys are, as shown in Fig. 1, arranged in rows, the keys in every other row being, in order to save space, displaced laterally by 80 half the distance between the keys in each row. Each key consists, as shown by Figs. 29 and 30, of an erect arm 5 on the upper end of which there is a button marked with a figure. The arms 5 are rotatably mounted 85 on shafts 6 fixed in the frame and are provided with pins 7, which at their free ends support metal cheeks 8 which can pivot on the pins. The cheeks 8 are connected with each other by means of plates 9, in which 90 are formed oblique grooves 10, with which the lower ends of the arms 5 engage. Thus if a key is pressed down, it turns the shaft 6, the upper part of the arm 5 meanwhile moving backward (Fig. 1^a) along a groove 11 95 provided in the casing, and the lower end of the arm 5 turning the cheeks 8 and the transverse plate 9 to one side or the other, depending on the direction in which the groove 10 runs. The lower ends of the 100 cheeks 8 are fork-shaped and embrace the registering wheels 12, which can move longitudinally but not rotate on shafts 13 rotatably mounted in the frame. Thus, when the keys are operated upon and the cheeks 8 105 are thereby shifted laterally in the manner described above, the registering-wheels 12 are brought into gear with transmitting-wheels 14, which are more fully described below. 110

The arms 5 are provided with heels 15, which extend backward and sidewise (Fig. 29). In two adjacent rows of keys these projections stand out at opposite sides (inward) from the two rows, so that they lie 115 in a straight line running between the two rows of keys, as seen in Fig. 29. Between every adjacent pair of rows of keys is placed a steel spring or the like 16, which passes over the shafts 6 and under the heels 15, as seen in Fig. 30. It is fixed at its ends and is just long enough to allow only one key at a time in each double row to be pressed down. When a key is pressed down the heel 15 of the same is lowered and presses down the 120 spring 16, so that the latter is fully ex-

tended and the heels of the other keys pressed upward causing these keys to stand erect as shown in Fig. 30. The object of this is thus to prevent more than one key at 5 a time from being pushed back, and thus more than one registering-wheel 12 from being in gear with a transmitting-wheel 14. When a key is moved backward and downward, a detent 17 on the upper part of the 10 key-arm engages a spring catch 18, fastened to the casing, so that the key is held down in its rearmost position. When another key in the same double row is afterward actuated, its heel 15 presses down the spring 16, causing 15 such a tension therein that the key previously actuated is released from the catch 18 by the pressure of the spring 16 on its heel 15, and returns to its original position.

On each of the shafts 13 there is an octagonal brake-disk 19 (Fig. 12) engaging with spring 20 fixed in the frame. The springs 20 tend to engage flat portions of the disks as shown in the figure, and if, when the shafts stop, the disk is in some other position, it is thus compelled by the spring to 25 continue, till the same, and shaft 13 with it, occupy a position such that the spring lies along a flat of the disk. When the brake-disks and also the shafts 13 occupy these 30 positions, the wheels 12 occupy such positions that the teeth thereon, when the wheels are pushed to one side, can freely engage the teeth of the transmitting-wheels 14.

On one side of each transmitting-wheel 5 there are four registering-wheels 12 and on the other side five (Fig. 43). There are no corresponding registering-wheels for the zero-keys since the transmitting-wheels will not be operated upon when registering a 10 cipher. The zero-keys only serve, when a cipher is registered, to bring a depressed key 40 in the same row back to its original position, in order that the registering-wheel belonging to it may be disengaged from the 45 corresponding transmitting-wheel.

Associated with each group of registering-wheels placed on each side of the transmitting-wheels are two register-sectors 21 and 22 (Figs. 2, 18, 19, the position of a pair of 50 sectors is also indicated on Fig. 2) which are rotatably mounted on a stationary shaft 23 in the frame. One sector is intended for even and the other for odd figures, and each sector is connected with a cylindrical part 24, around which passes a band suitably of 55 steel, which serves for turning the sector in question. Pins project from the cylinders and fit into holes provided in the bands, so that these may not slip.

On the curved side the sectors are provided with figures. Thus in Figs. 18, 19 the upper, left sector 21 is provided with the figures 0, 2, 4, 6, 8 and is operated by the band 25, which is placed over the even num-

bered keys. The lower right sector 22 is 65 marked with the figures 1, 3, 5, 7, 9 and is connected with the band 25 which is laid over the odd keys. The bands are inserted between projections 26 on the keys, and on the bands catches 27 (Figs. 2 and 30) are 70 provided which are acted upon by the projections 26 on the keys when the latter are moved backward, whereby the band is also drawn back a little and the sectors 21 and 22 respectively turned till the figure corresponding to the actuated key is brought forward opposite a viewing opening 28 (Figs. 1^a and 2) in the casing. The catches 27 on the bands are located in such a manner that they are brought forward just so far that, 80 when the different keys are pushed backward, the number corresponding to the key comes opposite the opening 28. For this purpose the catch 27, which corresponds to the key 1, is placed a short distance from 85 said key's position of rest, so that when the key is pushed back it first moves a short way in the opening 11 before it comes into contact with the corresponding catch 27, as seen on the right side of Fig. 2, since it only 90 needs a slight turn of the sector to expose the figure 1. The uppermost catch 27 (farthest to the left in Fig. 2), is, on the contrary, in contact with the key in its position of rest, since it must drive the band 25 so far 95 forward as to turn the sector 22 sufficiently to expose the figure 9 at the opening 28. By this arrangement the number can be read off in the openings 28 which has been registered in the machine by pressing certain keys 100 backward, and it can be ascertained whether the required number has been correctly registered. This registering mechanism does not form a part of the present invention.

(2) THE CALCULATING MECHANISM.

105

The calculating mechanism, which in simple positive or negative calculation in certain cases performs positive, or positive and negative, in certain cases negative movements, consists as shown on the drawings, of a cylinder C (Fig. 2) having two end plates 29 and 30, nine calculating-rings 31 and also eight distance pieces 32. Each calculating-ring 31 (Fig. 3) comprises twenty sections, 110 so-called calculators 33. Nine pairs of calculators *i. e.* 18 calculators, correspond to the digits 1-9 and one pair, *i. e.* 2 calculators, correspond to naught. These calculators being not provided with any teeth but are 115 plain. Such a calculator is shown separately in Figs. 4 and 5, and consists of two plates, between the upper part of which is inserted a sector 35, the outer edge of which carries oblique teeth 36 (Figs. 2, 3, 4, 5, and 120 7) varying in number between 5 and 1 (except that for constructional reasons one calculator is provided with 7, and four with 6

teeth). Some of the calculators also have no teeth as is more particularly described hereinafter. Between the plates 34 there is arranged at about the middle a pin 37 which 5 passes through the plates and is riveted to them, which pin supports a roller 38. At the lower end of the calculator there is also a similar pin 39 which supports a roller 40. Twenty such calculators are connected 10 so as to form one ring as shown in Fig. 3. A band 41, suitably of steel, passes over the rollers 38, the length of which is made such that two diametrically opposed calculators can at the same time be radially protruded 15 to a small extent by the arms 53 described below, the rollers 38 pushing the steel band outward so that two diametrically opposite bulges 42 arise therein (Fig. 3). Nine such calculating-rings 31 one for each digit 1-9 20 are assembled so as to form the calculating cylinder C (Fig. 2), distance pieces 32 being arranged between the adjacent calculating-rings separating, in order to space the same, the whole being mounted between the end 25 plates 29, 30. The whole is held together partly by means of thick rods 43 and partly by thinner rods 44. The rods 43 are riveted to the distance pieces 32 and are also riveted or held fast by nuts on the end plates. At 30 two diametrically opposed points the steel spring 41 is fastened to the rods 43 by means of pins 45 (Fig. 3).

On the end plate 30 is arranged a separate distance piece 46 and a calculating-ring 47, 35 the latter being shown separately in Fig. 6. This calculating-ring resembles the calculating-rings 31, although of less diameter. As seen, the rods 44 fit into this ring, though they are not of round cross-section here but 40 of such section that they fill the spaces between the calculators. Other connection rods 48, the diameter of which must be adapted to the distance between the uniformly broad inner shanks of the calcula- 45 tors, are provided as shown in Fig. 6. In the calculating-ring 47 the calculators, the oblique teeth and other parts are indicated by the same references as in the rings 31. The calculating-ring 47 is also shown de- 50 veloped in Fig. 7.

Through the calculating-cylinder C run two shafts 49 and 50, of which the last named is tubular and surrounds the shaft 49 (Figs. 2, 3, 9, 10); ball-bearings are ar- 55 ranged between the shafts. The shaft 50 is connected, by means of keys 51, with sleeves 52, from each of which an arm 53 projects. Such an arm with two diametrically op- 60 posed shanks is situated within each calcu- lating-ring and is of such length that its ends pressing against the rollers 40, can cause two diametrically opposite calculators to protrude from the cylinder. In order to distribute the work in the machine the arms

should be suitably placed in relation to one 65 another as indicated by Fig. 3 and also marked by thicker step-like lines in Fig. 7. To each of the ten simple multipliers 0-9 belong firstly a series of nine calculators for the tens and secondly a series of calculators for the units. Thus, by turning the cylinder in relation to the arms 53, when these are at rest, it can be adjusted so that the diametrically opposed calculators which belong to a certain factor or one-figured 70 multiplier, are pressed out at the same time by the arms 53. When multiplication by 4 is to be performed for example, the calculating-cylinder is turned in relation to the arms 53 standing still on this occasion in 75 such manner that all the pairs of calculators corresponding to the multiplier 4 are pro- truded by said arms.

In Fig. 3 are shown a part of the front calculating-ring in section, and also a section through the shafts 49 and 50, and the arms 53 in elevation in the position they occupy in the calculating-cylinder. In Fig. 3 only four arms are visible, which is due to the fact that the second arm lies just be- 80 hind the first, the fourth and fifth directly behind the third, the seventh and ninth di- rectly behind the sixth, while the eighth (the left in Fig. 3) is alone; in the part of the calculating-ring corresponding to the 85 tens, however, the ninth arm lies behind the eighth, and then a catch projects from the ninth, which catch lies behind the seventh arm, as indicated by the dotted curved line. In Fig. 3 are shown, besides parts of the 90 first calculating-ring, the calculators of the calculating-rings corresponding to the vis- 95 ible arms 53, said calculators being pushed out by the latter. Thus, the protruded cal- culators shown in Fig. 3 belong to the first, 100 third, sixth and eighth calculating-rings.

In the ring 47 (Fig. 6) is placed an arm 105 54 which differs from the arms 53 inasmuch as it only pushes out one calculator. The shaft 50 is square at the place where it goes 110 through the arm 54, and the hole in the arm is so large that a space 55 is left which allows the arm 54 to be displaced on the shaft 50, so that either one end or the other 115 of the arm can be made to push out a calcu- lator. The transferring of the arm 54 from one position to the other is performed by means of a pin 56 projecting from one of its shanks, and which fits into a groove 57 120 in a disk 133 (Fig. 11) on the shaft 49. The groove 57 has the form of a spiral-shaped 125 curve, so that one of its ends (the upper in Fig. 11) lies nearer the center than the other. Thus when the disk 133 is turned so that the pin 56 is brought over to the oppo- site (upper) end of the groove 57, the pin 56 is drawn toward the center and by this means the arm 54 is made to move outward.

- so that its opposite end will push out a calculator. In positive calculating operations the arm 54 presses out a calculator on one (the right, Fig. 6) side of the ring and in negative operations one of the calculators on the left side. The arrangement just described has the following object. If for example one has been adding and passes to subtraction by turning the crank in the contrary direction, the arrangement serves to perform, in spite of the altered direction of rotation, continual transference of the number of operations with the calculating-ring 47 to the quotient registering-wheels.
- 15 The shaft 49 is journaled in the frame-parts 59 and 60. On the end of said shaft which is turned toward the frame-part 59, a toothed wheel 61 is arranged, and on the shaft 50 a toothed wheel 62, and in addition 20 a toothed wheel 63 is fixed to the cylinder C. These toothed wheels 61, 62, 63 are respectively in gear with toothed wheels 64, 65 and 66 of which the toothed wheel 64 is arranged on a shaft 67 which at its opposite 25 end is fixed to the crank handle 70 (Fig. 1, left side, and Fig. 2). The toothed wheel 65 is arranged on a tubular shaft 68 (Figs. 2 and 34) which surround the shaft 67, and which, at its opposite end, supports the 30 change-over device 71 (Figs. 37, 35) for the arms 53, 54 (Figs. 3 and 6). The toothed wheel 66 is arranged on a tubular shaft 69, which incloses the shaft 68 (Fig. 37) and which at its other end supports the change-over arrangement 72 (Figs. 2 and 34) for the calculating-cylinder. All these shafts 35 run on ball-bearings.
- Rotation of the calculating-cylinder is brought about by turning the crank 70. The 40 teeth of the protruded calculators, will then operate toothed wheels 74 (Fig. 1), which are fixed on the same shafts 13 as the registering-wheels 12. As two opposite calculators in each calculating-ring are always 45 forced out by the arms 53, (one of said calculators being adapted for calculating the tens and the other for calculating the units of a partial product) all wheels 74 and at the same time all the shafts 13, are set in motion in one direction or the other, according 50 to the position of the oblique teeth 36 on the protruded calculators. At the same time, however, only the shafts 13 whose corresponding keys have been actuated to bring 55 the registering-wheels 12 into gear with the corresponding transmitting-wheels 14, will drive the wheels 14, and thereby transmit the calculating movements through the calculating mechanism.
- 60 The calculating-ring 47 serves, as indicated above to register the number of operations when adding and subtracting, the multiplier figures when multiplying, and the quotient when dividing. On adjusting the 65 cylinder C for multiplication by a certain

factor the ring 47 is at the same time automatically adjusted so as to protrude the calculator corresponding to said factor. If for example the cylinder C is adjusted for multiplication by 7, the 7 calculator in ring 47 70 is also protruded. The calculator forced out in the above ring 47 coöperates with a toothed wheel 75, the teeth of which consist of pins provided with round heads (called pin-wheels) on a shaft 76 (Figs. 1 and 8). 75 On the opposite end of this shaft is arranged a toothed wheel 77 (Figs. 1^a and 8). Right in front of shaft 76 there is another shaft 94 supporting eight toothed-wheels 79 each of which is provided with the figures 0-9 80 (Fig. 8). Each of these toothed-wheels 79 by a displacement of the carriage described later, can be brought into gear with the toothed wheel 77 on shaft 76. The wheels 79, as shown in Fig. 8, are provided with 85 sleeves the figures being written on the circumference of said sleeves. It is on these wheels 79 that the number of operations, multiplicator and quotient can be read; they are called the quotient registering-wheels. 90

As the oblique teeth on the calculators in the calculating-ring 47, as shown by Fig. 7, are placed so that with numbers between 5 and 9 the toothed wheels 75 and 77 and also the quotient registering-wheels 79 (Fig. 8), 95 when the partial multiplier or quotient is greater than 5, go the shortest way, i. e. backward, and as in this manner the figure 9 by a step backward is brought up on the quotient registering-wheels in question, 100 wrong numbers would be indicated if in this case "carrying" took place. For this reason means are provided for disengaging the carrying mechanism, which is effected in the illustrated construction of the machine by 105 turning a shaft 80 (Figs. 1, 1^a and 13) a quarter-of a revolution, so that a projection 81 on this shaft assumes its uppermost position as shown in Fig. 13. Transfer does not then take place. 110

If on the contrary the shaft 80 is turned so that the projections 81 occupy the position shown on Fig. 13 by dotted lines, the carrying will be performed by the mechanism provided for the purpose. The latter 115 comprises a triangular spring 82 fixed to each wheel 79 at the point of which spring there is a pin 83 so positioned that, when a wheel 79 revolves it normally does not touch the neighboring wheel 79 (Fig. 44^a). If on 120 the contrary the projection 81 is brought down (full position, Figs. 13 and 44^b), then, when the spring 82 passes the said projection during the revolution, this spring is laterally deflected (left side, Fig. 1) so that 125 the pin 83 is held in engagement with the next wheel 79 to the left till the spring 82 has passed the projection 81, whereby the said next wheel of higher order is moved for one tooth, to effect the transfer. As soon as 130

the spring 82 has passed the projection 81, it again moves out of engagement with the above-mentioned wheel 79.

In the calculating machines used up to 5 the present it is customary for each quotient registering-wheel to be marked with the figures 0-9-1. This arrangement is certainly simple but is attended with the inconvenience that in continued addition, after 10 having completed nine additions, the figure 8 in the quotient registering-wheels is brought up instead of 10, figure 7 instead of 11 and so on. Thus one cannot directly read off the number of additions when they exceed 15 nine. However, as it is often of importance, for example in election counting, to count the number of additions (number of voters) the quotient registering-wheels 79 in this machine are, as stated, marked with 20 the figures 0-9, and provided with the above-described carrying mechanism, so that in continued addition the number of additions can be read off at any time. This makes 25 the machine particularly suitable for counting election results, particularly in proportional voting systems.

As indicated above the number of operations in repeated additions or subtractions continued in one direction, or in mixed additions and subtractions, can be continually registered on the quotient registering-wheels 79 by adjustment of the arm 54, on account of the pin 56 fixed on the latter being put into engagement with the groove 57 35 in the plate 133 (Fig. 11).

(3) THE CARRIAGE.

The carriage comprises a part normally stationary when calculating and a part 40 movable when calculating. The stationary part consists of a bar 84 (Figs. 5, 40 and 41) which can be moved in a groove in the base plate 3 of the machine. A standard 85 (Fig. 1^a) is fastened to the right end of this 45 bar, and supports one end of a square hollow shaft 86. It is of course not necessary that the shafts should be square, they can also be round. Inside this shaft is arranged another square movable shaft 87, the free 50 end of which is supported by a second standard 88 fastened to the left side of the base plate 3. Thus the shafts 86 and 87 together form a telescopic shaft, which, always before a calculating operation begins, is extended by drawing the bar 84 with the right bearing 85 and the shaft 86 to the right. The carriage is then kept in this drawn out 55 position during the calculating. At the left side, Fig. 1, the inner shaft 87 supports one of the sides 89¹ of the carriage. The other side 89², which is bent inwardly at its lower end in order to allow room for the standard 85, supports the outer shafts 86.

The sides of the carriage are held together by a number of transverse shafts,

90, 91, 92, 93, 94 and 80 of which 90, 91 and 92 are riveted to the sides, and 93, 94 and 80 journaled therein. The side plates are also held together by two bars 95 and 96 (Fig. 40), the purpose of which is indicated 70 in the following. These side plates and shafts with the wheels supported by them make up the movable part of the carriage.

On the shaft 93 are fixed sixteen rotatable figure-wheels 97 at the same distance from 75 each other, and called result registering-wheels in the following, since the result of calculations is indicated on them. In the closed position of the carriage shown in Figs. 1 and 1^a (which it occupies only when calculating is not executed) the eighth result registering-wheel 97, which are situated on the right half of the shaft 93, are in front of the transmitting-wheel 14 which in the machine illustrated are eight in number. 80 If the machine works to ten digit numbers, ten transmitting-wheels are used and twenty result registering-wheels, and so on. When on the contrary the movable part of the carriage is fully drawn out, which is always 85 the case when calculating, the eight left hand result registering-wheels lie in contact with transmitting-wheels 14, and between these two outer positions any other 90 8 result registering-wheels can, during the 95 movement of the carriage, be successively brought into contact with the transmitting-wheels. The upper portion of the movable part of the carriage (Fig. 40) can be tilted a little outward (to the right in Fig. 40) 100 around the shaft 86, 87, so that the result registering wheels 97 and the quotient registering wheels 79 on said movable part are brought out of gear with the transmitting wheels 14 and the toothed wheels 77 respectively on the still standing part of the machine. The purpose of this tilting of the carriage and the manner in which it is carried out are more fully described in the following. 110

The result registering-wheels 97 are, similar to the quotient registering-wheels 79, furnished with a part 98, provided with a sleeve projecting from the wheel proper and on whose outer edge the figures 0-9, 0-9 are 115 marked (Fig. 13). In order that the wheels 97 may always be arrested in such a position that their teeth can be freely engaged with the teeth of the transmitting-wheels, they are provided with a brake arrangement which consists of internal wave-like projections 99 on the sleeve 98, and which, according to the drawing, meet at the middle of each tooth. A wedge-pointed pin 100 having its shank passing through the shaft 120 93 and acted upon by a spring, cooperates with the projections 99 and when the movement of the wheel is stopped engages a depression between the wave-like parts. If the wheels have stopped in a wrong posi- 125 130

tion the point of the pin 100 under the influence of the spring, enters one of the above-mentioned depressions whereby the wheel is always brought to a correct position.

On the shaft 86, 87 is fixed a cylinder 101, which serves to perform the above-mentioned movement of the carriage in the manner stated below. The cylinder spoken of 10 (Figs. 1, 1^a, 40, 41) consist of a brass tube which is provided with two end walls. In the left end wall Fig. 1, a hole is made, into which the inner shaft 87 fits, and in the right end wall there is a hole into which 15 the outer shaft 86 fits. The holes are, so adapted that the cylinder 101 can easily be displaced longitudinally on the shaft 86, 87 when the carriage is in motion. Between the bearing 88 and the carriage wall 89' 20 there is a roller 102 attached to the shaft 87 and one end of a steel-band, chain, or the like 102¹ is fastened to said roller. The other end of this band is fastened to a sector 103 (Figs 41 and 42), which can turn 25 on a shaft 104. The turning of this sector is brought about by a cam-disk 132 fixed on the cylinder shaft 49 and which actuates a roller 105 on an arm 106 projecting from the sector 103, to bring the arm 106 and with 30 it the sector 103 periodically into the position shown by dotted lines in Fig. 42, the steel-band 102¹ being unrolled so that the shaft 86, 87 and at the same time the cylinder 101 rotate, the cylinder 101 turning 35 through exactly one revolution. When the downward movement of the cam disk 132 on the roller 105 has ceased, the latter and also the sector 103 and the cylinder 101 are brought back to their original position by 40 means of a spiral spring 107 (Figs. 1, 2 and 41) fixed to the sides 89¹ of the carriage at one end and to the cylinder 101 at the other.

45 *Carrying mechanism.*

The surface of the cylinder 101 is provided partly with a helical groove 108, which in a machine adapted for eight-figured numbers makes eight turns around the cylinder and has the same pitch as the distance between two transmitting-wheels, 14, and lying in planes normal to the axis of the cylinder. The cylinder also has fifteen circular grooves 109 (Figs. 1, 1^a, 11) placed 50 at equal distances from one another. Each of these grooves 109 has a bulge 110 (Figs. 1 and 1^a) and those bulges are so placed with relation to each other that they lie along a helical line on the surface of the 55 cylinder 101. The grooves 109 are deeper than the helical grooves 108. On the surface of the cylinder 101 there are also fifteen projections 111 (Figs. 2 and 40) placed along a helical line parallel to the helical 60 line which passes through the bulges 110.

In the circular grooves 109 are inserted the ends of a series of levers 112 (Figs. 1, 1^a and 40) pivotally mounted on the cover plate 113 of the carriage. The other ends of these levers engage grooves 114 (Fig. 15) provided in toothed sectors 115 fixed on the stationary shaft 92, of which toothed sectors there is one for each result registering-wheel, with the exception of that situated farthest to the right in Fig. 1. An arm 116 70 projects downward from each sector, 115. Immediately to the side of the sectors 115 are wheels 117 fixed on the same shaft 92, which can turn about 1/6 revolution in either direction on the shaft 92. The wheel 80 75 117 is kept in its extreme positions by the aid of springs 118 (Figs. 16, 17) which press their ends provided with pins 120 into shallow holes 119 in the shaft 92, in order to make the shafts and, consequently, the sectors 115 occupy proper positions for meshing with the wheels 97. A feather 121 projects (to the left of Fig. 16) from the wheels 117 and extends into a groove in the sectors 115, so that these sectors are connected with 85 the wheels 117, and can thus turn about 1/6 revolution around the shaft 92, and in addition are displaced along the latter, when they are guided by the feathers 121. This displacement takes place through the influence of the levers 112, at the instant when 90 their lower ends enter the bulges 110 of the grooves 109, which causes the levers to pivot so that their upper ends along with the sectors 115, are shifted to the left (Fig. 1) 100 when the sectors are brought for a moment into gear with the next higher order result registering-wheel 97 to the left, which is turned forward one step to effect the transfer.

This carrying is brought into use when the result registering wheels are turned through more than 9 teeth or steps in the same direction, which can occur, if, for instance, a wheel in a previous calculating operation has been turned forward 6 teeth and the wheel is afterward turned four teeth more. Two springs 123 provided with hooks 122 project from each wheel 117 and two diametrically placed pins 124 and 125 (Figs. 115 17 and 40) project from the result registering-wheels 97. When, in positive calculating, the pins on the wheels 97 have turned 9/20 of a revolution (the wheels 97, Figs. 2 and 40, then rotate clockwise) and have 120 reached the hooks 122, one pin 125 slips over the inclined back of the hook, the spring yielding outward, while the other pin 124, on the contrary meets the flat underside of the hook 122 and carries the hook with 125 it slightly, whereby the wheel 117 and also the sector 115 are turned clockwise by one step, and the arm 116 (Fig. 40) brought to the left, Fig. 45. The sector remains in this position until a carrying operation is to take 130

place, after which it is pushed under the next result registering-wheel 97 to the left by the lever 112 belonging to it, such levers being guided on this occasion by the curve 5 110 on cylinders 101.

Directly under the sectors 115 partly toothed sectors 126 and 127 (Figs. 40, 45 and 46) are journaled on the stationary shafts 90 and 91, and are kept by a spring 10 128 in the normal position shown on the drawing. Each of these sectors is provided at the top with an arm 129 and 130, and one sector 127 is provided with a spring 131. When, during the rotation of the cylinder 15 101, the corresponding projection 111 on said cylinder encounters the spring 131 (Fig. 46) the sector 127 and also the sector 126 in gear therewith, are revolved so that the arms 129 and 130 of these sectors approach 20 each other and actuate the arm 116 (Fig. 46) whether the latter, in positive carrying, is in its left extreme position, or in negative carrying in its right extreme position, thus bringing the said arm back to normal position 25 (shown in Fig. 40). The sector 115, which is at this moment in gear with the result registering-wheel normally situated to the left of it, now makes this wheel turn one step, so as to show 1, and at the same 30 time the carrying is performed. The same course is afterward performed successively on account of the curves 110 lying along a spiral line on the cylinder 101 repeated with all the other sectors 126 and 127, the arms 35 129 and 130 of which are thus moved toward each other twice during each revolution of the crank 70 whether their sector 115 is brought over to one side or remains in its normal position, that is to say, whether the 40 carrying with the respective sectors 115 takes place or not.

Instead of the carrying mechanism shown in Figs. 14-17 one can also use the modified construction of the same, which is illustrated in Figs. 38 and 39. In the last mentioned construction the wheels 117 and appertaining springs 123 are omitted and replaced by toothed wheels 333 keyed on a shaft 331, the pins 124 and 125 (Fig. 40) being also replaced by two diametrically opposed teeth 332 located on the result registering-wheels 97 (only one tooth being shown in Fig. 38). These teeth gear with the wheels 333, when the result registering-wheels pass from 9 to 0, thereby turning the wheels 333 for the distance of one tooth in one direction or the other, depending on whether the carrying is to be performed in a positive or negative direction. The wheel 55 333 gears with teeth provided on the sectors 115, which are, thus, also turned for the distance of one tooth, so that the arms 116 will also be turned, as described above in connection with Figs. 14-17 and 45, in one direction or the other. When afterward the 60 65

sector 115 is displaced to the left by the arm 112 and is brought into gear with the teeth on the next result registering-wheel 97, the sector is brought out of gear with the wheel 333 so that, when the arms 129 and 130 are 70 moved toward each other (same position as in Fig. 45) for turning the sector back to its normal position (same position as in Fig. 40), the said result registering-wheel is turned for the distance of one tooth without acting upon the toothed wheel 333. On returning the sector 115 to its original position it is immediately again thrown into gear with the wheel 333. In order that the 75 wheels 333 may always be held in proper position with relation to the teeth of the sectors 115 and to the teeth 332 on the wheels 97 they are suitably acted upon by springs 343 (to be indicated in Fig. 38) attached to stationary parts of the machine and engaging with their free ends between the teeth of said wheels. 80 85

(4) THE MECHANISM FOR BRINGING ABOUT MOVEMENT OF AND IN THE CARRIAGE. 90

The movement of the carriage serves to move the quotient and result registering-wheels, the former in relation to the tooth wheel 77 and the latter in relation to the transmitting wheels 14, so that the calculation of the tens, which is carried out during the first half revolution of the calculating-cylinder C, will be executed by a wheel to the left (Fig. 1), of the units, which are calculated during the second half revolution of 95 the calculating cylinder. 100

By turning the calculating-cylinder C by means of the crank 70, the shafts 50 and 49 running through the cylinder, and also the groove and cam elements supported by them 105 are turned. On the end (the right Fig. 2) of the shaft 50 (see Figs. 9, 10, 11) is fastened a groove and a cam disk 132, while two cam disks 133 and 134 and also a cover-plate 135 which is immovably fastened on 110 the disk 134 are placed on the end of the shaft 49 projecting from the shaft 50. These disks are used to transfer movement to the cylinder 101 belonging to the carriage, and which has partly a rotating and 115 partly a linear movement.

(a) Mechanism for imparting rotary movement to the cylinder 101.

As stated above the cylinder 101 belonging to the carriage is at times made to revolve in order to bring about displacement of the movable part of the carriage. It has also been indicated that the said rotation is brought about by means of a sector 103 in 120 the manner that a cam disk operates a roller 105 placed on an arm 106 projecting from the sector 103. 125

This cam disk is the disk 132 on the shaft 50. As shown in Fig. 9, this disk is pro- 130

vided with two diametrically opposed cams 136 and 137. The places of union between the circular part of the disk and the cams 136 and 138 are denoted in Fig. 9 by 138, 5 141, 142 and 145 respectively, and the angles or corners of the same by 139, 140, 143 and 144 respectively. The complete course of the disk 132 over the roller 105 for each whole turn of the crank, is thus the course 10 138, 145, 144, 143, 142, 141, 140, 139, 138, and the roller will thus be pressed down twice for each revolution (Fig. 2) so that the cylinder 101 will revolve twice. In 15 positive calculating the cams 136 and 137 occupy the original position shown in full lines in Fig. 9, and the disk 132 rotates counter-clockwise. In the original position the roller 105 is at 138, and when the crank is turned and the disk 132 rotated, the part 20 of the course 138—145 passes the roller, during which the result registering-wheels 97 are turned. In the subsequent part 145—144 of the course the pressing down of the roller will be effected whereby the arm 25 106 is pressed down and the sector 103 brought into the position shown in dotted lines in Fig. 42, so that the steel band 102¹ is unwound, and the cylinder 101 turned one revolution. At the same time in conse- 30 quence of a tooth 150 on a lever 147 described hereinafter engaging the helical groove 108, the cylinder is displaced by one step to the left owing to the lever 147 being fixed as regards the axial direction of the 35 cylinder. The result registering-wheels are thereby turned a step to the left, and in addition the carrying takes place through the influence of the levers 112 on the projections 111. During the part 144—143 of the 40 course the roller 105 is not shifted and the cylinder 101 stands still, and meanwhile the calculating-ring 47 turns the wheel 75, by which the shaft 76 (Fig. 8) and also the 45 wheels fixed on it are rotated so that the quotient registering-wheels 79 are turned and at the same time movement is transmitted to the printing mechanism for the printing of the quotient as is more fully described hereinafter. During the next portion 50 143—142 of the course the roller 105 is actuated, and the cylinder 101 turned back a revolution, that is, to the original position, through the influence of the spiral spring 107 (Fig. 41), the spring 131 (Fig. 55 40) sliding meanwhile idly over the projections 111. During the portion 142—141 of the course the roller 105 is idle and the result registering-wheels 97 are turned for calculating the units. In the next part 60 141—140 of the course the roller is actuated and the cylinder 101 turned one revolution, but without the movable part of the carriage being brought forward, the projection 150 not being in gear with the groove 65 108. During this rotation of the cylinder

101 thus only the carrying (ten transference) takes place by means of the levers 112 and the projections 111, in the manner described above. In the part 140—139 of the course 140—139 no work is performed 70 in the machine. Finally during the part 139—138 of the course the carriage, when the machine is adjusted for addition, is brought one step backward to the original position, while in multiplication the last 75 named movement of the carriage does not take place.

When the machine is to be used for performing negative calculating, for instance subtraction, it is adjusted for such mode of 80 calculating by turning the shaft 50 a quarter of a revolution in a counter clockwise direction by means of bar 203 and disk 71 (during which the shaft 49 stands still); at the same time the disk 132 is also turned 85 so that the cams 136 and 137 are brought from the position shown in full lines to that shown with dotted lines in Fig. 9. The cam 137 will then be brought into contact with the roller 105, so that the starting 90 point of the movement of the roller during negative calculating operations will be the point 145. When the crank 70 is turned, the disk 132 will rotate clockwise and thus the different points of the course will pass 95 the roller 105 in the following order, namely, 145, 138, 139, 140, 141, 142, 143, 144, 145, whereby the operations, which are described above for positive calculating, will be carried out in the same order. 100

(b) *The mechanism for imparting linear movement to the cylinder 101.*

As just previously indicated the cylinder 101, has, in addition to a rotating movement, 105 also a linear movement, when the whole of the movable part of the carriage is moved with it. This movement has for its object, as stated, the separation of the calculating of tens and units performed on a certain 110 transmitting wheel, so that during the first half revolution of the calculating cylinder, the tens will be transferred from the transmitting-wheels to the result registering-wheels which for the moment are in front of 115 the transmitting wheels, after which, on account of the linear movement of the carriage to the left performed during an intermediate stage, the units are brought over to the next result registering-wheel to the 120 left, which has now come in front of the transmitting wheel in question. In addition the linear movement has for its object, in addition and subtraction, the bringing back of the carriage, during the last part of 125 a revolution, to the original position, thus to the right, Fig. 1.

The arrangement for bringing about this linear movement is the following:—

From a shaft 146 (Fig. 2) which is jour- 130

naled in standards 60 and 149 (Fig. 1) projects an arm 147, provided with a tooth 150 adapted to engage the helical groove 108 of the cylinder 101, and also in the opposite 5 direction an arm 148, one end of which runs in the following course formed by the disks 133 and 134. Projections 151, 152, 153, and 154 are arranged on the disk 133, Fig. 11. The course in question is also bounded by 10 the circumferences of the disk 134 and by two slide-bars 155 and 156, which can be moved in grooves provided in the disk 134. The disk 134 is connected with the shaft 49 by means of a key 157 fixed in this shaft 49, 15 but so that the disk can, on account of the keyway in it being wider than the key 157, turn through a certain angle around the shaft 49. This angle must be so large that when 20 the disk 134 turns, the slide-bars 155 and 156 can alternately be brought to bear against the projections 151 and 153 (as on the figure) and against the projections 154 and 152.

The positions of the slide-bars 155 and 156 25 are regulated according to the desired mode of calculating in such a way that in addition and subtraction they are both projected, that is to say that they occupy the position shown in Fig. 11, while in multiplication 30 a slide-bar 155 is projected and the slide-bar 156 is drawn into the disk 134, while in division the slide-bar 156 is projected and the slide-bar 155 is drawn in.

This movement of the slide-bars is brought 35 about in the following manner:

As indicated above, the disk 132 is keyed on the shaft 50 supporting the arms 53, while the disks 133 and 134 are keyed on the inner shaft 49. When adjusting the 40 cylinder C for the desired mode of calculating in the manner described in the following under heading 5 (Mechanism for adjusting the machine for the desired mode of calculating), the shaft 50 is turned by 45 means of the change over device 71 (Fig. 1) while the shaft 49 remains still, since the crank 70 is then stationary. At the same time a relative turning between the disk 132 on one hand and the disks 133 and 134 on the 50 other thus ensues. The pins 158 and 159 projecting from the slide bars 155 and 156 run with play through the disk 133 and enter a horse-shoe shaped groove 160 (Fig. 9) in the disk 132. In each end of this 55 groove is mounted a spring 161, 162, fixed at one end, the two springs bearing yieldingly against the inner wall of the middle part of the groove 160 with their free ends lying at some distance apart. There are also at 60 the ends of the groove 160, two other springs 163 and 164 which are similarly fastened to the disk 132 at one end, while their free ends bear yieldingly against the springs 161 and 162.

65 In adding, both the pins 158 and 159 and

the groove 160 occupy the positions shown on Fig. 9, with the two slide-bars projecting as in Fig. 11. If one wishes to pass to subtraction, the disk 132 is turned a $\frac{1}{4}$ revolution counter clockwise, the thicker end of the 70 spring 161 comes in front of the pin 158, while the middle part of the groove 160, situated between the ends of the springs, comes before the pin 159. In this position both the slide bars are still drawn out. 75

If one wishes to pass from the position for addition shown in Fig. 9 to multiplication, the disk 132 is turned a small angle clockwise so that the pin 159 comes into contact with the spring 164. If the turning is 80 continued the pin 159 is then pressed by the spring 164 in the direction toward the center, so that, when the disk 132 is afterward turned back the same angle, the pin 159 will slide along the inside of the spring 162 and 85 stop in front of the position shown in Fig. 9. The pin 158, during this movement moves a little forward on the outside of the spring 161 and then back to the position shown. 90

If one wishes to pass from the previously described position for subtraction to the position for division, precisely the same movements take place as in passing from addition to multiplication, although in the 95 opposite direction.

If one wishes to pass from the position for division to the position for addition the disk 132 is turned a $\frac{1}{4}$ revolution clockwise, when the pin 158 (which is then on 100 the inner side of the spring 161) slides along this inner side, presses the spring 161 outward during the last part of this movement, and finally slides outward, so that when the movement stops the pins 158 and 105 157 will be in the position shown in Fig. 9.

The two slide-bars 155 and 156, operating in the manner of railway point gear, by both or only one of them being held projected, cause the end of the arm 148 to pass along 110 different courses, according to the mode of calculating that the machine is for the moment to carry out.

The different courses which the end of the arm 148 will traverse, are as follows for the 115 different modes of calculating.

Addition.—The position for addition is shown in Fig. 11. The crank 70 is turned clockwise and thus the disks 133 and 134 will rotate counter clockwise, that is to say 120 in the direction indicated by the arrow in Fig. 11. The arm 148, whose end is indicated by a circle in Fig. 11, will then, during the first part of the turning of the disks 133, 134, rest against the circumference of the disk 134, whereupon the oblique surface of the slide-bar 155 comes into contact with the arm 148 and presses it outward so that the said arm will, during the following part of the revolution, rest against 125 130

the outer surface of the projection 151. When this projection has passed the arm, the latter again moves inward and during the next part of the revolution, it will rest 5 against the edge of the disk 134 until the slide-bar 156 comes into touch with it and presses it outward to the outer edge of the projection 153. When this projection has passed the arm 148, the latter is again 10 moved inward to rest against the edge of the disk 134, and at the same time the revolution is completed. When, during the rotation of the disks, the arm rests against the outer sides of the projections 151 and 153, 15 the arm 148 (Fig. 2) is pressed downward and the arm 147 brought against the cylinder 101, so that the tooth 150 on the said arm is brought into the helical groove 108. Since the arm 147 and the tooth 150 are now 20 standing still, the rotation of the cylinder 101 will provide shifting of the latter to one side or the other. This moving of the cylinder 101 takes place at the same time that the roller 105 on the lever 106 is depressed 25 by the cam 136 or 137, the cylinder 101 is thereby made to rotate as described above.

Subtraction.—When subtracting, the slide-bars 155, 156 are also kept projected, although they then rest against the projections 154 and 152 respectively, due to the fact that the disks 133, 134, rotate in opposite direction to the arrow in Fig. 11. If, however, the slide-bars, when setting said disks in motion, are not brought over to the 30 positions just mentioned for some reason or other, they are subsequently brought over to said positions on account of the play mentioned around the key 157 as soon as they push against the arm 148. The latter will then, during the movement of subtraction, follow this course; the circumference of the disk 134, the slide-bar 156, the outer side of the projection 152, the circumference of the disk 134, the slide-bar 155, 35 the outer side of the projection 154, and then it falls in toward the center to the original position.

Multiplication.—Only the slide-bar 155 is projected, the course during the counter 40 clockwise rotation of the disks 133, 134, being then the circumference of 134, the slide-bar 155, the outer side of the projection 151 and also the circumference of the disk 134 to the starting point.

Division.—Only slide-bar 156 projected. The course will be: circumference of 134, slide-bar 156, outer side of 152, circumference of 134 and back to starting point.

During the calculating of both multiplication and division the arm 148 (Figs. 2 and 11) is thus pressed downward and the tooth 150 thus introduced into the groove 108, only once for each turn of the crank 70, that is to say, during these modes of cal-

culating the cylinder 101 is only moved once 65 for each turning of the crank and this to the left (Fig. 1). This movement of the cylinder takes place when the arm 148 rests against the outer side of the projection 151 or 152 respectively. The movable part of 70 the carriage is thus not brought back (*i. e.* to the right, Fig. 1) at the end of each revolution in the two last mentioned calculating operations, since the tooth 150 does not engage the thread 108 and the arm 148 is 75 not brought to the outer sides of the projections 153 and 154 respectively, as in addition and subtraction, but follows the circumference of the disk 134 during the second half of each revolution. 80

(c) *Periodical releasing of the carriage from the transmitting wheels.*

When the movable part of the carriage moves, in the course of calculating, in one 85 direction or the other, the result and quotient registering-wheels must be free from the wheels which drive them during the calculation. This takes place in the present form of construction by means of the upper 90 part of the carriage which, as stated, can turn about the bearings of the shaft 86, 87, being brought to occupy a position slightly inclined forward (outward to the right, Fig. 40).

This inclining of the carriage is brought about by the following arrangements: On the front edge of the disk 132 are formed four raised parts 165, 166, 167 and 168, which are indicated on Fig. 9 by means of shading. 95 A roller 171 (Figs. 2 and 42) carried by an arm 172 rolls along the said edge of the disk 132, and is brought outward (to the right, Fig. 2), when the above projections pass it, thereby turning the pivot shaft 173 100 of the arm 172 so that two arms 174 (Figs. 2, 1^a and 42) and 176 (Fig. 1^a) fixed on said shaft and also rollers 175 (Figs. 2, 42 and 1^a and 177 (Fig. 1^a) respectively, fixed on said arms, are brought outward to the 110 right (Fig. 2) thereby forcing outward the cross bar 95 of the carriage, so that the upper part of the carriage inclines to the right (Fig. 2) sufficiently that the result and quotient registering-wheels are disengaged from the wheels which drive them. The said tilting of the carriage is limited by a suitable projection (not shown) on the front side of the machine and fastened to the casing 2. The carriage is tilted outward in the manner stated four times during each revolution, but during the rest of the time of the revolution the carriage occupies the normal position, so that the quotient and result registering-wheels engage 115 the wheels which drive them. 120

During addition the quotient registering-wheels are driven, when the roller 171 passes

the part 169 of the course between the two raised projections 165 and 166, and during subtraction when the same roller passes the part 170 of the course between the raised projections 167 and 168.

In passing from one mode of calculating to another the forced out calculators of the cylinder C must be prevented from imparting movement to the wheels 74 which movement would continue to the result registering wheels. This result could be obtained by first adjusting the machine to zero (when the arms 53 press out the calculators which are not provided with inclined teeth). As, however, such an adjustment is time consuming the present machine is provided with an arrangement for automatically obtaining said result by tilting the carriage outward and consequently, without adjusting the machine at zero. Such a turning of the carriage in normal cases takes place through the influence of the raised projections 165, 166, 167 and 168 on the roller 171 (Figs. 2 and 42), as described above. When passing from one mode of calculating to another it is necessary, however, that the carriage should be tilted outward even when the roller 171 passes the part 170 of the course (Fig. 9). For this purpose between the raised projections 165 and 168 a groove 179 is provided in the side wall of the disk 132 (Figs. 9 and 9^a). This groove which is concentric with the circumference of the disk 132 and extends over 90°, is deeper at the ends so that a pin 181 which is attached to a spring 180 fixed to the raised projection 154 (Fig. 11) and which extends through a hole in the disk 133, when it reaches the ends of the groove 179, it can lie entirely therein, allowing the spring 180 to lie tightly against the raised projection 154. The middle of the course 179 is shallower so that in front of the course 178 the pin 181 is thrust so far outward that it moves the extensions 182 of the arm 172 (Figs. 2 and 42) so far outward to the side, that the rollers 175 (Figs. 1^a and 2) and 177 (Fig. 1^a) displace the bar 95 (Figs. 2 and 40) and incline the carriage outward disengaging the result registering wheels 97 from the transmitting-wheels 14.

While the crank 70 is turned for carrying out the different calculating operations the disks 132, 133 and 134, rotate simultaneously, and the pin 181 is then at one end or the other of the groove 179. When passing from one mode of calculating to another, on the contrary only the disk 132 is turned, while the disks 133 and 134 stand still. It is thus during this movement of the disk 132 that the track 179 in the disk operates the pin 181 and pushes it outward with the above indicated result.

5. MECHANISM FOR ADJUSTING THE MACHINE 65 FOR THE DESIRED MODE OF CALCULATING.

As indicated above each of the shafts 67, 68, 69 has a manipulating device, namely the handle of crank-arm 70 and the change-over devices 71 and 72 respectively (Fig. 34). By means of these devices either the shaft 69 alone, or the shafts 69 and 68 together, or all the three shafts together, can be rotated in order to carry out the operations previously indicated, that is to say, in the first case the turning of the cylinder C through the medium of the wheels 66 (on shaft 69) and 63 (see Fig. 2), so that the series of calculators which corresponds to the number of additions indicated by a partial multiplier stops in front of the arms 53, which are on this occasion at rest and will then push out the calculators in question. In the second case, *i. e.* when the two shafts 69 and 68 are turned at the same time motion is transmitted simultaneously to shafts 49 and 50 (by wheels 66, 63 and 65, 62 respectively) and thus to the cylinder C and the arms 53 as hereinbefore described. Both the calculating cylinder and the arms 53 being turned together, the protruded tens calculators in negative calculating come to the left, and in positive calculating to the right of the wheels 74 (Fig. 95 1). In the third case, *i. e.* when all three shafts 69, 68 and 67 are turned together, the calculating operations are carried out, and here exactly a whole revolution is always performed, while in the first and second cases the turn can comprise larger or smaller parts of a revolution.

The turning of the shaft 69 alone, performed in the first case mentioned above, and at the same time of the calculating cylinder C, is determined by means of a disk 72 keyed to the said shaft (Fig. 34). In the disk 72 there is a circular groove 183 in which there is a steel spring 184 run over rollers 185 (Figs. 34, 35). In the disk 72 there are ten keys 186 which can turn on pins 187, which keys are marked 0, 1, 2-9, 0, as seen in Figs. 1 and 35. The upper ends of the keys are provided with small number plates while the lower ends 188, 115 when a key is actuated, move forward and enter a groove 191. From the edge of the disk 71 project catches 192 and 193 (Fig. 35) which are situated such a distance apart that the lower end 188 of a key can be inserted between them. The said catches are supported by springs 194 and 195 respectively which are fastened by one of their ends to the circumference of the disk 71, in which there is a recess, so that the catches 120 can yield toward the center of the disk, when, during the rotation of the disk 72, the lower end 188 (Fig. 34) of an actuated

key comes into contact with one of the said catches. When the lower end 188 of a depressed key engages between the catches 192, 193, the disks 72 and 71 are connected 5 with each other, so that, when the crank 70 turns for carrying out a calculating operation both the shaft 68 which is connected with shaft 67 by a rod 205 indicated below, and the shaft 69 connected with shaft 68 by the depressed key, will turn at the same time as indicated in the third case mentioned above.

From the keys 186 projections 189 extend backwardly, and, when on depression 15 of a key engage catches on springs 190, which are fastened to the edge of the disk 72, and of which there is one for each key. The depressed key is thereby held in this position. There are also other projections 20 196 on the keys 186, which, when a key is depressed, press downward pins 197 (Fig. 34) which can move in the disk 72. These pins in their turn operate upon the above mentioned spring 184, which is then extended, and restores any previously actuated key to its normal position. This arrangement thus works in similar manner to the spring 16 associated with the keys 5.

Two spiral springs 198 and 199 (Figs. 30 34, 36) working in opposite directions are fastened at their inner ends to the shaft 69. The outer ends of these springs are slidably attached to a ring 200 running concentrically with the shaft 69, this ring being common to both the springs. The manner of slidably fixing the ends of the springs consists in threading the ends of the springs through staples 201 on the inside of the ring, the springs being prevented from being drawn out of these staples by means of stops 202 at the ends of the springs. The ring 200 supporting the springs, can, by means of one or several bolts 203, be fastened to a stationary standard 204. The object of these spiral springs is that, when multiplying, it shall not be necessary to turn the calculating cylinder C by hand to the different positions required by the partial multipliers, but that one or the other 15 of the springs 198, 199, according to the direction in which the crank 70 is turned, and after having been strained by the turning of the crank, and by depression of a key 186 with consequent release of the shaft 69, will turn backward said shaft 69 and with it the calculating cylinder so that the latter is automatically brought to occupy the position corresponding to the last depressed key, that is to say, the calculating 20 cylinder is adjusted for multiplication by the figure indicated on the last depressed key. Then, as stated, only one spring works, for example 198, while the other spring 199 is at the same time pushed freely

through the staple 201, wherefore it will 65 not exercise any influence on the shaft 69. On the contrary when the crank 70 is turned in the opposite direction the spring 199 is strained and, when a key is depressed, 70 makes the shaft 69 and with it the calculating cylinder, turn to the position to which the number on the key depressed corresponds, while the spring 198 is freely pushed in the manner indicated through the staple 201 without operating the shaft 69. 75

This arrangement has for its object the simplifying of the registering of the partial multipliers in multiplying, and the division when dividing. In repeated addition and subtraction this arrangement is not 80 used since these modes of calculation can be regarded as positive or negative multiplications by 1 and in this case in the above described arrangement would of course be a hindrance, since for every calculating operation it would then be necessary to depress the key marked 1. In addition and subtraction operations the bolt 203 is therefore drawn out, and the ring 200 freed so that it follows the movements of the shaft 69. 85 In multiplying and dividing on the contrary, the bolt 203 is pushed in so that the ring 200 is connected with the upright 204 and will thus stand still during calculating operations, while one of the springs 198 and 199 is strained in the manner indicated above. Thus, if the springs are not strained i. e. before the first turn of the crank during each mode of calculating, this disk 72 will not move but must be turned by hand 90 till the projection 188 of the depressed key slips in between the catches 192, 193. 95

For illustrating this arrangement a simple example is given here, namely the multiplication of 235 by 27. The number 235 is 105 first set up on the key board of the machine by depressing the keys 4 which are marked 2, 3 and 5. It is further supposed that the 6-key on the disk 72 has been pressed down in a foregoing operation and stands pressed down at the beginning of this calculating operation. One of the springs 198, 199 had, in the above described manner, been strained when the crank 70 was turned in the foregoing operation and is, 110 thus, continuously held strained by the lower end 188 of the actuated 6-key preventing the disk 72 from rotating. 115

In multiplying the registered number 235 by 27 the 2-key on disk 72 is first depressed, 120 whereby the previously depressed 6-key is brought back to its original position by spring 184, pin 197 and projection 196. The disk 72 is thereby released and rotates through the influence of the above mentioned 125 strained spring (198 or 199) until the lower end 188 of the 2-key slips in between the catches 192 and 193, whereby the rotation

- of the disk is stopped. The cylinder C has by this rotation been adjusted for multiplication by 2. The crank 70 is then turned a revolution after which multiplication by 2 is performed. Then the 7-key on disk 72 is depressed, whereby the 2-key is brought back to its original position, thereby releasing the disk, which is then brought to rotate until the lower end 188 of the 7-key slips in between the catches 192 and 193, whereby the rotation is again stopped and the cylinder C now adjusted for multiplication by 7, this multiplication being performed when the crank 70 is then turned a revolution.
- 15 It is evident that, for the purpose of making the machine simpler, the springs 198 and 199 can be altogether dispensed with, in which case every adjustment of the disk 72 must be done by hand. Similarly the keys 20 on the disk 72 and the springs 194 and 195 with the catches 192 and 193 can be removed. In this case, however, the figures 0-9 must be set out on the disk 72 and the disk 71 provided with an index, or vice 25 versa.

Adjustment of the machine for required mode of calculation.

As stated above the shafts 69 and 68 can 30 also move together (second case), the calculating cylinder and the arms 53 thereby also moving together, while the groove and cam disks 132 supported by the shaft 50 turn on the shaft 49 relatively to the disks 133 35 and 134, which stand still during these operations.

From the disk 71 an arm 73 projects, which supports a sector-shaped bar 205 (Fig. 1) with shanks of equal size on each 40 side of the arm 73. These shanks are slightly yielding and provided with two catches or are formed with grooves 206 and 207 respectively for receiving the crank-arm 70. By now bringing the crank-arm 70 into 45 one of the grooves 206 or 207 (or by connecting the crank-arm in some other way with one of the ends of the bar 205) the machine can be adjusted for the required mode of calculating in the manner indicated 50 below.

For instance, when passing from addition to subtraction the disk 132 must, as stated above, be turned $1/4$ of a revolution in the counter clock wise direction. This is obtained by turning the disk 71 by means of the bar 205, $1/4$ of a revolution in the clock wise direction, (on account of the connection mentioned between disk 72 and disk 132, these disks will rotate in an opposite 55 direction. The clock wise turning of the disk 72 will thus impart a counter clock wise turning to disk 132.) The position of addition of disk 72 and bar 205 is shown in Fig. 1. Consequently, in passing from addition

(bar 70 in groove 206) to subtraction, the 65 groove 206 is released from bar 70 and the bar 205 is turned clockwise until the bar 70 slips into the groove 207.

Twelve different combinations are possible as shown by the following table, where A 70 means addition, S=subtraction, M=multiplication, and D=division.

Positions and movements of the arms.

Trans-ference from—	Released from en-gagement with the crank.	Direction of movements.	Brought into en-gagement with the crank.	75
(1) A to S...	206	Clockwise $1/4$ revolution.....	207	
(2) A to M...	206	Counter clockwise $1/12$ revolution; clockwise $1/12$ revolution.	206	
(3) A to D...	206	Clockwise $1/4+1/12=4/12$ revolution; counter clockwise $1/12$ revolution.	207	
(4) S to A...	207	Counter clockwise $1/4$ revolution.	206	85
(5) S to M...	207	Counter clockwise $1/4+1/12=4/12$ revolution; clockwise $1/12$ revolution.	206	
(6) S to D...	207	Clockwise $1/12$ revolution; counter clockwise $1/12$ revolution.	207	
(7) M to A...	206	Clockwise $1/5$ revolution; counter clockwise $1/5$ revolution.	206	90
(8) M to S...	206	Clockwise $1/4$ revolution.....	207	
(9) M to D...	206	Clockwise $1/4+1/12=4/12$ revolution; counter clockwise $1/12$ revolution.	207	
(10) D to A...	207	Counter clockwise $1/4$ revolution.	206	
(11) D to S...	207	Counter clockwise $1/5$ revolution; clockwise $1/5$ revolution.	207	95
(12) D to M...	207	Counter clockwise $1/4+1/12=4/12$ revolution; clockwise $1/12$ revolution.	206	

As an aid to the remembrance of the above adjustments there are signs for the different modes of calculating, and arrows cut in the bottoms of the tracks 206 and 207 and on the disk 71, as shown in Fig. 1. 100

(6) MECHANISM FOR INDICATING THE SYMBOL FOR THE MODE OF CALCULATING FOR WHICH THE MACHINE IS ADJUSTED.

In order to obviate mistakes in the adjustment of the machine for a certain mode of calculating there is an arrangement which shows the symbol for the mode of calculating for which the machine is adjusted. The following is the arrangement: Between the 110 calculating ring 47 and the disk 132 (Fig. 2) there is, on the square part of the shaft 50, a partly toothed wheel 406 (Figs. 1 and 2) with a radius so large that it gears with a toothed wheel 407 which is connected with 115 a smaller toothed wheel 208 (Figs. 1 and 32) which in its turn gears with the teeth of a rack 209. In a groove 210 running along the lower part of this rack there is a movable pin 211 (Figs. 1 and 32) carried by a 120 horizontal bar 212, whose left enlarged and hollow part 213 provided with an oblique surface can be operated by a pin 214 car-

ried by the crank-handle 70, and which pin, when the crank is in its position of rest, is pressed into a hole in the standard 204 (Figs. 1 and 2) and at the same time operates a rod 215 (Fig. 2), which, on account of its obliquely cut end co-operating with the oblique surface on the part 213, in its turn moves the bar 212 slightly to the left (Figs. 1 and 32), so that the rack 209 gears with the wheel 208. When the machine is to be set for another mode of calculating, by readjustment of the bar 205 in the manner described above, the toothed wheel 406, and also the toothed wheels 407 and 208 are turned a certain angle. On account of the rack 209 being geared with the wheel 208, this rack is now made to move in a straight line in one direction or the other. The rack 209 at its upper end is connected by the slotted end 217 (Fig. 2) of a two-armed lever 216 pivoted on a rod 218, which lever upon the said movement of the rack is rocked. In one arm of the lever 216 is a slot 219 (Figs. 37 and 37^a) in which one end of a pin 221 (Figs. 2 and 37) enters, the other end of which fits into a similar slot 222 in a shank of a piece 223 (Fig. 37) carried on the lever 216. One end of a lever 220 (Figs. 2, 37 and 37^a) which can turn on a pivot 224, is attached to the pin 221 which projects on both sides of the said lever. The extreme end of the lever 220 fits into an 8-shaped groove 225 in a plate (Figs. 1, 37 and 37^a) extending downward from the machine frame. On the other end of the lever 220 there is a sector 226 (Figs. 1 and 2) in whose curved end turned outward in Fig. 1 the signs —, :, +, × are indicated at different heights, Fig. 1, and can be brought forward one by one in front of an aperture in the casing. The manipulation of the sector 226, and thus the exposing of the different symbols in front of the said aperture takes place in the following manner: When the rack 209, in passing from one mode of calculation to another by changing over the bar 205, Fig. 1, is brought upward for example by the toothed wheel 406 engaging wheel 407 (Fig. 1), the right end of the lever 216 (Fig. 2) is raised, along with the slot 219 and the pin 221 engaging therein, and thus also the end of the lever 220 connected with the pin 221 is raised. When the end of this lever slides in the 8-shaped groove 225 so that the opposite end of the lever 220 with the sector supported by it are turned in the opposite direction, i. e. downward, the minus sign appears. If the rack is brought a little higher upward (corresponding to the 1/12 revolution indicated in the table) a spring 227, Fig. 37, presses the pin 221 over to the opposite side (left) of the 8-shaped track 225, so that the division symbol appears in the window.

When passing to positive modes of calcu-

lating the same course is followed, although in the opposite direction. Movement of the sector 226 takes place quite automatically when the bar 205 is changed over, thus when the crank 70 is at rest. As soon as the crank 70 is liberated, by withdrawing the pin 214 from the hole in the uprights 204, in order to rotate said crank for carrying out a calculating operation, then the bar 212 is pushed to the right (Fig. 32) by the spring 228, the rack 209 being thereby brought out of gear with the toothed-wheel 208. When adjusting for the subtraction or division, the rack 209 is in its uppermost position, and when the rack is freed from the wheel 208 the lower catch 229 on the rack engages a stationary projection 231 in the machine, which supports the rack. When adjusting for multiplication or addition, the rack is in its lowest position, on account of which, when the rack is freed from the toothed wheel 208, the catch 230 engages the projection 231 in order to support the rack.

(7) THE PRINTING MECHANISM.

The printing mechanism is employed for making it possible to verify that the correct numbers have been used in the course of the calculation. Therefore not only is the result printed by the printing mechanism, but also the items, the multipliers, etc., so that there are printed on a strip of paper un-wound from a roller, firstly the numbers which have been registered on the key board, namely the items, the multiplicand or the dividend, secondly the numbers which successively appear in the quotient register during the course of the calculation, namely, the multiplier, the quotient, or the number of items which are added or subtracted, thirdly the sign of the mode of calculation in question, fourthly the decimal point, and finally the sum, the remainder, the product or the quotient.

The registering or recording of that which is thus printed takes place in the following stages:

(1) When adjusting the machine for the mode of calculation to be employed, the registering of the symbol in the printing mechanism takes place on a sector intended for that purpose.

(2) The decimal point is registered.

(3) When registering the items, the multiplicand, or the divisor by depressing the keys in the key board, the keys operate the steel-bands 25 and transfer movement to the printing mechanism.

(4) The numbers appearing in the quotient register are successively registered during the course of the calculation through the direct transference of movement to the printing mechanism.

(5) The result is set up on the key-board by pressing down the corresponding keys.

- This operation has for its object to transfer the result to the printing mechanism for printing, and also, due to the machine being at this moment adjusted for subtraction, for verifying that the last result set up on the key-board corresponds to that which is before indicated by the result register, and consequently, that the correct result is printed. This checking is of course made possible on account of the fact that, in carrying out the subtraction, the remainder in the result register must be zero, if the result is correct.
- (1) *Arrangement for registering the symbols of the modes of calculating in the printing mechanism.*
- In describing the mechanism for showing the symbol of the mode of calculating for which the machine is for the moment adjusted, the two-armed lever 216 was mentioned. This lever continues on the other side of the pivot 218 and is forked at this end, the shanks 233 and 234 inclosing a bar 235 (Figs. 1, 21, 22 and 33), in which an 8-shaped groove 236 is formed which in its construction and its manner of working is similar to the groove 225. With this groove 236 engages one end of a lever-arm 237 by which the sector 232 is manipulated. On one shank 233 of the lever 216 there is a spring 238 which has as its object to shift laterally a pin 239 running through the arm 237, whereby the arm 237 is moved to one side or the other. The pin 239 passes through a slot 240 in the shanks 233 and 234. The sector 232, which is pivoted on the rod 241, is connected with the lever-arm 237. The sector 232 consists of a middle part from which project firstly the curved arms 245 and 246 (Fig. 33) and secondly the part 247, the edge of which is provided with two grooves 248 and 249 which co-operate with a rule 250 which is more fully described below. Between the arms 245 and 246 extends a bar 251 which serves as pivot for two rollers 252 and 253, which are provided with three teeth on a quarter of their periphery. Opposite the two outermost teeth types are placed for printing the symbols for the different modes of calculating, one roller being provided with types for addition and multiplication symbols and the other with the types for subtraction and division symbols. These rollers 252 and 253 lie in front of a part 244 provided with three screw-threads and which by means of the side-parts 242 and 243 is fastened to the rod 241. One of the teeth on the rollers 252 and 253 always gears with one of the threads on the part 244, so that when the lever 237 by its engaging the 8-shaped groove 236, is brought to one side or the other, the rollers 252 and 253 are at the same time revolved so that the required symbol on one roller or
- the other arrives directly under the ribbon 254 (Fig. 33) in the printing mechanism, and is afterward printed at the end of such calculation together with products, results and so on, as is more fully described in the following:
- (2) Registering of the decimal point in the printing mechanism is described under the next heading (3).
- (3) *Registering of the items, the multiplicand, and the divisor (Fig. 2) in the printing mechanism.*
- This registering is brought about by the steel-bands 25, which, on turning of one of the sectors 21 and 22 (Fig. 2), turn one of the corresponding toothed sectors 256 or 257 which are journaled on a stationary spindle 258 in the machine frame. The teeth of these sectors operate the toothed wheels 259. These wheels are as much wider (Fig. 1^a) than the two sectors together as the breadth of a ring provided for the decimal point (see below). As the wheels 259 must necessarily be placed at such a great distance from each other that they cannot be used as type-wheels, extra type-wheels 260 placed near each other must be arranged for bringing the types together at a convenient distance from one another, and each of these wheels is, by means of tubular shafts 261 (Fig. 20) placed inside each other, connected with a corresponding toothed wheel 259. When registering an even figure on the key-board a sector 256 for the even figure in question is turned clockwise and with it the corresponding wheel 259 counter clockwise, and when registering an odd figure the sector 257 corresponding to the desired odd figure is turned counter clockwise and the corresponding toothed wheel 259 clockwise. On account of the connection between the toothed wheels 259 and the type-wheels 260 the latter turn in the same manner as the wheels 259, and therefore the type which corresponds to the key operated upon will be placed under the ribbon 254.
- In order to reduce the friction, each of the tubular shafts 261 is, at its ends, provided with circular bearings 262, which parts alone are in contact with the next shaft.
- Registering of the decimal point in the printing mechanism.*
- In this machine the decimal point can be registered between any figures, and this registering is done at the beginning of a calculating operation. This registering is done by bringing in at the desired place between any type-wheels 250, a ring 263 provided on its edge with decimal point types. On Fig. 20 this ring, which is narrower than the type-wheels, is brought in between the third and fourth type-wheels from the left. The ring is split and the halves are

connected with each other at one end by a hinge, and at the other end provided with a convenient locking arrangement. In order to allow the ring 263 to be inserted between the type-wheels 260, the latter and the shafts 261 and the toothed wheels 259 are movable in relation to each other. On account of this, the toothed wheels 259 must be so much wider than the sectors 256 and 257 together as the breadth of the decimal point ring as previously indicated.

(4) *Registering in the printing mechanism of the numbers appearing in the quotient register.*

This registering is brought about by the following mechanism: On the shaft 76 (Figs. 1^a, 8 and 40) there is, in addition to the above-mentioned toothed wheel 77, a wheel 264 (Fig. 8), which, when it is turned an equally great angle as the wheel 77, transfers movement to the printing mechanism by means of a steel-band 266 placed around the wheel 264 (Fig. 8) and a similar wheel 265 (Figs. 1^a, 8 and 27). The wheels 264 and 265 can be provided on their edges with pins and the band 266 with holes, so that it will not slip. The wheel 265 is fixed on a square shaft 267. On this shaft a pinion 272, attached to eight sharp-edged connected rings 271, can be displaced longitudinally (Figs. 23 and 27). The shaft 267 is pivotally mounted in the front ends of two arms 268, 269 connected to each other, the back ends of which are pivotally mounted on a spindle 270 (Figs. 1, 2, 23 and 27) so that the front ends and at the same time the shaft 267, and the rings 271 can be raised or lowered. This raising and lowering which is carried out once every time the crank 70 is turned when multiplying or dividing, has for its object in these modes of calculating the displacing of the pinion 272 one step to the left, which is performed by the rings, when rising and falling, being brought in touch with stationary edges 291 and 292 (Figs. 21, 22), so that the rings and also the pinion 272 which, when beginning multiplication and division lies at the extreme right in Fig. 1, or topmost position, Fig. 27, are successively displaced laterally so that the pinion 272 is geared with and turns one wheel 273 (Figs. 1 and 23) after the other, which wheels are mounted to the number of eight on a shaft 274 pivotally mounted in the machine frame. The rings 271 and, consequently, the wheel 272 are displaced step by step on shaft 267 (Fig. 27) due to the fact that the edges 291 and 292 are displaced in relation to each other so that they do not line in the same vertical plane (as is shown in Fig. 22 and hereinbefore set forth). Consequently, when the rings have been raised and touch the upper edge 291, this one will slide on the sloping

surface of a ring. As a result, the rings and the wheel 272 are displaced as much as half the distance between the edges of two adjacent rings. When the rings are then lowered and brought into contact with the edge 292, which then comes into contact with the sloping surface on the adjacent ring, the rings are again displaced as much as half the distance between two adjacent rings. The edges are thus displaced in relation to each other as much as half the distance between the edges of two adjacent rings.

In this manner, the wheel 272 is displaced step by step so as to come into contact with one after the other of the wheels 273 (Fig. 24). The wheels 273 are not displaced. The wheels 273 turn type-wheels 275 (Figs. 1 and 2) placed on a shaft 276 journaled in the machine frame, and this shaft extends through the innermost tubular shaft to the type-wheels 260 and the toothed wheels 259.

In adding and subtracting the pinion 272 and also the rings 271 stand farthest to the left (Fig. 1) and do not leave their places during the course of these calculations, since in the latter it is necessary only to register the number of calculating operations, additions and subtractions, in the printing mechanism, the pinion-wheel 272 then standing still in front of the wheel 273 (Fig. 1) farthest to the left. Movement is then continually transmitted to the shaft 267 by means of the band 266, while the pinion 272 is turned for the distance of one tooth for each revolution of the crank 70. On this occasion the toothed wheel 273 is also made to carry out a similar movement and when it has been turned one revolution, carrying is effected by a mechanism similar to that used in the quotient registering-wheels 79, and which consists of the springs 82 and pins 83. In the toothed wheels 273 the springs for performing the carrying are marked 277 and the pins 278 (Figs. 23, 24). In the quotient registering-wheels there is, as stated, an arrangement 80, 81 for bringing the carrying mechanism in and out of action. There is also a similar mechanism in the wheels 273, which consists of short arms 279 with a wedge-shaped section; there is one arm for each wheel and these arms are supported by a shaft 280 (Figs. 23, 24), which in its turn is supported by two arms 283 projecting from a rock shaft 282, the turning of which can be caused by an arm 281. In operations of multiplication and division, the arms 279 occupy such a position that they do not touch the springs 277, and no carrying takes place. On the contrary in addition and subtraction operations the arms 279, by means of the arm 281, are brought into such a position that when the springs 277 with the pins 278 pass the arms, 279, the pins 278 are pressed in between the teeth in the 130

neighboring wheels 273 and bring them forward by one step. When the springs 277 have passed the arms 279 the springs return to their usual position of disengagement.

- 5 The raising and lowering of the arms 268, 269, mentioned before, is brought about in the following manner: From the arm 268 a smaller arm 284 projects laterally and supports a small roller 285 (Figs. 23 and 27). This roller 285 rests against the edge of a cam-disk 286 (Fig. 28) fixed on a square part of the shaft 50 which runs through the calculating cylinder. This cam-disk has the form shown in Fig. 28.
- 10 At one part of its edge there is a recess 287. In front of this there is arranged a slide-bar 288 by the radial projecting of which the recess can be filled. The slide-bar 288 is pushed in, *i. e.* the recess is empty when
- 15 multiplying and dividing, while during addition and subtraction, the slide-bar 288 is pushed out and the edge of the disk 286 is continuous. Between the points 289 and 290 where the recess is situated the disk is
- 20 of smaller radius than elsewhere.

As stated above, the rings 271 serve to effect the lateral movement on the pinion 272 by bridging the rings, when rising and falling into touch with the stationary edges 291 and 292, between which the rings 271 are arranged. The smaller radius of the disk 286 is so adapted that the rings, when the roller 285 is on the said part, can be displaced along the shaft 267 without touching any of the edges, whereby the pinion 272 does not mesh with the toothed wheels 273. The greater radius of the disk 286, on the contrary, causes the pinion 272, when the roller 285 is on this part, to gear with the wheels 273, and the upper edge 291 enters the groove between two adjacent rings. The recess 287 is so deep that, when the roller 285 lies therein, the lower edge 292 (Figs. 21 and 22) can reach the bottom

35 of the groove between two rings 271, and on account of the rings being pointed the lower edge 292 then causes the rings and the pinion-wheel 272 to be pushed laterally.

In adding and subtraction, when the slide-bar 288 fills up the recess 287, the rings 271, when the roller 285 is on the part of the disk 286 of smaller radius, lie just between the edges 291, 292, without touching them. When the roller 285 afterward arrives at

40 the part of the greater radius the rings are brought toward the upper edge 291. This is afterward repeated during these modes of calculation, so that the rings then oscillate between said position and in gear with

45 the upper edge 291, without displacement being effected (except in the first gearing, when a displacement of half a step takes place).

In multiplying and dividing, on the contrary, when the slide bar is drawn back, the

rings 271 occupy the mid position without touching the edge while the roller 285 is on the part of the cam disk of smaller radius, and when the roller 285 afterward enters the recess 287 the ring 271 is brought

50 against the lower edge 292, at which a displacement of half a step takes place. The roller 285 then arrives again at the other half of the cam, of the smaller radius, and the ring 271 reassumes mid position. After

55 this the roller 285 runs over the part of the cam with the greater radius and the ring 271 is lifted and pushed against the upper edge 291, while the other half step of the lateral shifting takes place etc. The

60 displacing movement is here made possible because one of the edges 291 and 292, as shown in Fig. 22, does not stand in front of the other, but is displaced laterally therefrom.

The moving of the slide-bar 288 is effected by means of a pin 293 which projects from it and enters a groove 294 (Fig. 25) in the toothed wheel 61 on the shaft 49. When the machine is adjusted for addition and subtraction, the pin 293 is in the outer part of the groove 294 (Fig. 25) nearest the edge of the toothed wheel 61, and the slide bar is then pushed out. When the machine is adjusted in the above manner for multiplication or division, the pin 293 is brought over to the inner part of the track 294, whereby the slide-bar 288 is pushed in.

(5) The registering of the result is described above under heading (4).

As it is possible, that on account of backlash that may occur in the machine, the types of the printing mechanism may not always lie in a straight line there is an arrangement for alining them. The arrangement for this purpose consists of the previously mentioned part 250 (Figs. 2, 23, 27, 33) which runs lengthwise under all the type-wheels 275 and 260 (Fig. 1). The part 250 is supported by two arms 295 and 296 (Fig. 27), which are pivotally connected with the arms 268 and 269 respectively. One arm 295, which is lengthened and bent outward, supports at its free end, a roller 297 which rolls on the edge of a cam-disk 298 (Figs. 2 and 47) on the shaft 49. The cam-disk 298 is of the same shape as the disk 286, except that there is no recess corresponding to 287 and the cam-disk is provided with two raised projections 299 and 300 (Fig. 47). When the roller 297 passes the raised projections 299 and 300, the part 250 is raised and inserted between the types in the type-wheels in such a manner that the types will be alined. The part 250 in reality only needs to be raised once during each revolution; in negative modes of calculation, however, when turning the crank counter clockwise, there must be two symmetrically placed projections, in order

that the raising of the rule will also take place after the adjustment of the type-wheels.

5 *Performing of the printing operations in the printing mechanisms.*

After the types have been set up or registered in the manner indicated above, the printing is carried out as follows: An arm 301 (Figs. 2, 26, 27) is fixed on the above mentioned spindle 270 journaled in the machine frame, which arm 301, at its free end, supports a roller 302 which can run either on the circumference of a disk 303 (Fig. 25) 10 fixed on the shaft 49, or on that of a disk 304 mounted in a recess in the disk 303. By means of a slide-bar 305, which can be retracted when the roller 302 is to roll on the edge of the inner disk 304, or extended when 15 it is to be transferred to the edge of the outer disk 303, the courses, which the roller 302 will follow, are automatically determined when adjusting the machine for the different modes of calculating. The arrangement of this slide-bar 305 and its manipulation is similar to that which is described above for the slide-bars 155 and 156 (Fig. 11). On account of angular clearance 20 allowed the key by means of which the disk 304 is keyed to the shaft 49, this disk can turn enough to allow the slide-bar 305 to lie against either one part 306 or other 307 of the cam course (Fig. 25). The position of the slide-bar is adjusted by means of a pin 25 308 which enters a groove 309 in the toothed-wheel 61 which operates similarly to the groove 160 which performs the adjustment of the slide-bars 155 and 156 (Fig. 9.) When the machine is adjusted for addition 30 and subtraction, the pin 308 is moved by the cam groove 309 so that the slide-bar 305 is pushed outward and brought to rest against one part 306 or the other 307 of the course. The roller 302 will thus run the 35 first half of the revolution on the inner disk 304 and is afterward pressed out by the slide-bar 305 on to the edge of the outer disk 303. When adjusting for multiplication or division on the contrary, the slide-bars are pressed inward by springs 310, 311, so that the roller 302 during these modes of 40 calculation, runs on the edge of the inner disk 304.

On the spindle 270 a disk 312 is keyed 45 (Fig. 27), so that it rotates with the said spindle.

In recesses 313 provided in said disk there are located friction rollers, 314, which press against the end wall of the cylinder 315 on 50 which the paper strip 318, to be printed upon, is wound. The spindle 270 extends through holes provided in the end walls of the cylinder 315, so that the cylinder can rotate on the said spindle. Consequently,

when the shaft 270 is caused to rotate, the 65 disk 312 rotates with the same, and, on account of the action of the friction rollers 314 also the cylinder 315 is caused to rotate. The friction force between the cylinder and the disk 312 becomes, however, 70 rather feeble when the disk stops, and if the spindle 270 and disk 312 stop only a feeble force is required to overcome the friction, so as to continue the rotation of the cylinder 315. Consequently, on stopping the rotation 75 of the spindle 270 the paper strip, would be torn off if a relative movement between the cylinder 315 and the disk 312 was not rendered possible by the friction rollers or similar devices. On stopping the 80 rotation of the spindle 270 the strain in the paper strip on the cylinder 315 will thus make the cylinder continue its rotation a little so that the paper strip will not be torn off under such strain. From the spindle 270 85 two arms 316 project, and these by springs 317 support a weight 255, along the underside of which is arranged a cork plate or the like 319.

If the starting position of the roller 302 90 is that indicated on Fig. 25, when the roller 302 has dropped from the edge of the disk 308 through an opening 320 between the parts 306 and 307 of the course at the end of a previous stage in the calculation, and 95 lies against the edge of the disk 304, then in addition and subtraction the roller 302 rolls on the edge of the disk 304 during the first half of the revolution. Then it is restored by the spring 311 (or 310) and the 100 slide-bar 305 to the edge of the disk 303 while the arm 301 is brought outward (upward Fig. 2). Then the disk 312 attached to the axle 270 is turned and takes with it, on account of the friction-rollers 313, 314, 105 etc., the cylinder 315, and the strip of paper 318 coming from a roller not shown, thus advancing said strip a short distance corresponding to a distance between the middle points of two adjacent rows of types. 110 When turning the spindle 270 as stated, the arms 316 are also brought outward and lift the weight 255 with the cork plate 319. At the end of the revolution, when the roller 302 drops through the opening 320 to the 115 edge of the disk 304, the spindle 270 is turned quickly back, at which, on account of the tension of spring 317, the weight 255 with the cork plate 319 presses the strip of paper and the ribbon 254 against the types 120 to effect the printing. Thereafter the parts immediately assume the normal position shown on the drawing.

When multiplying and dividing there is 125 no printing during the ordinary calculating, but only at the end of it. During these calculating operations the slide-bar 305 is therefore drawn in as stated above so that

the roller 302 will roll the whole time on the edge of the disk 304, on account of which the arm 301 will not be brought outward. At the end of these calculating operations 5 the weight 255 is lifted a little by hand and then released at which printing takes place in the manner indicated above.

Zeroizing the registers.

10 (1) Setting up or recording register (key-board). In this register zeroizing is performed by depressing the cipher key, as stated in the foregoing.

(2) The result register is zeroized by 15 means of the wing nut 322 (Fig. 1) attached to the shaft 93. The base of this wing nut is so formed that when being turned half a revolution, a bar 323 (Figs. 1 and 13), along with projections 324 and 326 (Figs. 13 20 and 40) thereon, is slightly retracted. At the ends of the projections are pins 325 and 327 respectively, which by the retraction of the bar are engaged with corresponding holes on all the wheels 97 and 79 which are 25 zeroized, while in the case of the remaining result registering-wheels they press against their sides. When the turning is afterward continued the wheels standing at zero are turned half a revolution, and on the other 30 wheels the pins slide until they drop into holes in the sides of the same, after which these wheels will successively take part in the turning to the zero position.

(3) The quotient registering-wheels are 35 brought back in the same way to the zero position by means of a wing nut 328, when the springs 326 and the pins 327 exert an effect similar to that of the springs 324 and the pins 325 just described. Here the wing 40 nut 328 must, however, be turned a whole revolution, since the quotient registering-wheels are only provided with the figures 0-9.

45 (4) *The register in the printing mechanism.*

(a) The type-wheels 260, which correspond to the setting up register on the key-board, are zeroized at the same time as the 50 setting up register on the key-board on account of the connection of the steel-bands 25 with the sectors 256 and 257.

(b) The type-wheels 275 are zeroized by 55 a steel band which is wound around a pulley (not shown) attached to the shaft 274.

(c) The rings 271 with the pinion-wheel 272 are brought back to the starting position (Fig. 27) by drawing a steel-band 600 or the like accessible from the outside of the 60 machine, and which is wound on a cylinder 329 attached to a toothed-wheel 330 (Fig. 22) which is in gear with the rings 271, the distance between the teeth on the wheel 330 being adapted to the distance between the

sharp edges of the rings 271. Through the 65 rotation of the toothed-wheel 330 which is brought about by drawing said steel band 600, the rings 271 can be made to return to their starting position.

Examples of calculations.

70 Before calculating is begun, it must be ascertained that the machine is set in the manner previously described for the mode of calculating desired.

Addition.—If for example the number 139625 and 66015 are to be added together, the number 139625 is first set up on the key board, besides which the key 1 on the disk 72 is depressed (addition being a multiplication by 1). In the setting up on the key-board four operations take place, firstly, when the different keys are depressed, any figures which may have been set up or registered before on the key-board are removed; 80 secondly, the wheels 12 associated with the depressed keys are geared with the corresponding transfer-ring-wheels 14, thirdly, the figures corresponding to the depressed keys operated upon, are turned in front of 90 the apertures of the register-sectors below the key-board, so that it can be ascertained whether the correct number has been registered, fourthly, the type-wheels 260 are turned so that the types corresponding to the 95 respective numbers are brought into the position for printing.

Then the crank 70 is turned a revolution clockwise. The number 139625 is then brought over unaltered to the result registering-wheels (it being presupposed that from the beginning the said wheels were at zero). Afterward the number 66015 is set up on the key-board and the crank 70 is again turned a revolution clockwise. At 100 the same time the last mentioned number is transferred to the result registering wheels and added to the former, so that the result 205640 can now be read off through the apertures in front of the result registering wheels. 110

Subtraction.—After the machine has been adjusted for subtraction as hereinbefore described, the operation is carried out in the same way as that of addition except that the crank 70 is turned a revolution in the 115 opposite direction, *i. e.* counter-clockwise. If there are only two numbers, for instance 329—5216, the subtraction operation, in which the remainder would be a negative quantity, is very seldom executed by machine. If, however, it is to be executed by machine, one must proceed in such a manner that the smaller number 329 is subtracted 120 from the greater number 5216, although one must in such a case bear in mind that the 125 result is negative. For example, 329—5216=—4987, this being the same as= (5216—329)—4987.

Multiplication.—An example of multiplication has been previously given in connection with the description of the key arrangement on the disk 72. A further example is now given. In ordinary multiplication, for example 47×237 , the numbers are set up and the calculation is carried out in known manner, thus:

$$\begin{array}{r}
 237 \\
 \times 47 \\
 \hline
 1659 \\
 948 \\
 \hline
 11139
 \end{array}$$

The calculation is thus carried out in such a manner that the figures of the multiplier taken from the right, successively multiply the figures of the multiplicand, likewise from the right. The partial products are further written down so that the units of the second partial product are written under the tens figure of the first product, and so on. When calculating by machine it is, however, more convenient to proceed in the contrary order, that is to say, so that the figures of the multiplier multiply those of the multiplicand in the order they are read. The calculating operation in the machine can thus be written in the following manner:

$$\begin{array}{l}
 4 \times 3 = 12 \\
 4 \times 7 = 28 \\
 4 \times 2 = 8
 \end{array}$$

Carriage moved one step to the left.

$$\begin{array}{r}
 7 \times 2 = 14 \\
 7 \times 3 = 21 \\
 7 \times 7 = 49 \\
 \hline
 11139
 \end{array}$$

This calculating operation carried out on the present machine with reference to the multiplication table previously given, can be written as follows:

$$\begin{array}{r}
 4 \times 2 = +I-2 \\
 4 \times 3 = +I+2 \\
 4 \times 7 = +III-2
 \end{array}$$

Carriage moved one step to the left.

$$\begin{array}{r}
 7 \times 2 = +I+4 \\
 7 \times 3 = +II+1 \\
 7 \times 7 = +V-1 \\
 \hline
 1 \ 1 \ 1 \ 3 \ 9
 \end{array}$$

The method of working may be further explained as follows:

If 372 (multiplicand) is to be multiplied by 7 (multiplier) this is executed in the following manner:

After having adjusted the machine for

multiplication in the manner described the following operations take place:

Firstly the multiplier 372 is set up on the key-board by pressing down the keys marked 3, 7 and 2. By pressing down these keys: (1) The keys having been pressed down in a previous operation are automatically returned to the original position by the action of the steel band 16, (2) the registering wheels 12 corresponding to the actuated keys are brought into gear with the corresponding transmitting wheels 14, so that the shafts 13 corresponding to said actuated keys are brought into operative connection with the crank, and, consequently, with the calculating cylinder.

Secondly the 7-key on disk 72 is depressed (for multiplication by 7). By pressing down said 7-key on disk 72 said disk and the shaft 69 supporting the same and, consequently, the calculating cylinder C, are turned so much in relation to the arms 53, which are on that occasion at rest that all the nine pairs of calculators 33 (Fig. 3) corresponding to the factor 7 are protruded by said arms.

Consequently, all the nine pairs of calculators being now protruded are adapted for multiplication by any of the digits 1, 2, 3, 4, 5, 6, 7, 8 and 9 by 7. The 7 calculator is also protruded in ring 47. Said pairs of calculators are thus provided with the following teeth (Roman figures indicate the teeth of the tens-calculators and Arabic figures the teeth of the units calculators, and the signs + or - indicate whether the units teeth have the same (+) as, or the opposite (-) direction to, the tens teeth):

$$\begin{array}{l}
 (1) I-3, (2) 1+4, (3) II+1, (4) III-2, \\
 (5) III+5, (6) IV+2, (7) V-1, (8) \\
 V+6, (9) VI+3.
 \end{array}$$

Thirdly the crank 70 is turned once to the right (clockwise). The calculating cylinder C is hereby also turned one revolution to the left (anti-clockwise). By this turning of the cylinder C all the nine wheels 74 are brought to rotate and also all the nine shafts 13 and the nine transmitting wheels 12 supported by the same are brought to rotate.

But only these shafts 13 which correspond to the depressed keys on the key board (thus in this case the shafts 13 which correspond to 3, 7 and 2), are, by means of the corresponding registering wheels 12, connected with the transmitting wheels 14, and, consequently, it is only these shafts 13 that transmit the movements to the result registering wheels. All the other shafts 13 which do not correspond to any depressed keys on the key-board are idly working.

In the above example 7×372 the protruded 7-calculators on the cylinder C reg-

ister, during the first half revolution of the same, the following tens: $+II+V+I$, and during the second half of the revolution, after the movable part of the carriage has been displaced one step, the following units: $+1, -1, +4$ are registered. The complete calculation performed by the machine can, thus be expressed as follows:—

$$\begin{array}{r}
 +II+V+1 \\
 + 1-1+4 \\
 \hline
 2 \ 6 \ 0 \ 4
 \end{array}$$

15 The result 2604 can then be read off in the result register. As multiplication is a positive calculating operation, the machine had before the beginning of the calculation, been adjusted (by means of bar 205 20 turning shafts 68 and 69 together whereby the cylinder C and the arms 53 are turned together) so that the tens calculators are placed to the right of the wheels 74. As the cylinder C in this mode of calculating 25 rotates anti-clockwise the ten calculators will, consequently, first act upon the wheels 74 (Fig. 1) and then the units calculators.

The other movements in the machine are exactly the same as described in the following, in calculating addition, for each quarter of the revolution of the crank except that, on account of the fact that in multiplying only the slide bar 155 is protruded, the arm 148 is pressed down only 35 once during each revolution of the crank, and consequently, the tooth 150 is inserted only once into the thread 108 of the cylinder 101. From this reason the movable part of the carriage is not returned at the end of the 40 operation when calculating multiplication (and division).

If there is one figure more in the multiplier, for example 3, the 3-key on the disk 72 is then depressed, whereby the previously actuated 7-key is automatically returned to its original position. By the movement taking place when depressing the 3-key the cylinder C is, as stated above turned over the arms 53, Fig. 3, (which 50 are on that occasion at rest) and when it stops all the pairs of calculators which are adapted for multiplying by 3, are protruded. Then the crank is again turned one revolution to the right and the same movements are repeated.

In multiplying the crank is, consequently, turned as many times as there are figures in the multiplier. Therefore, when multiplying, the number having the greatest number 55 of figures is preferably used as multiplicand and set up on the key board.

Division is carried out in a similar manner to multiplication, although the crank is turned counter clockwise. The dividend is

set up on the key board, the figures of the 65 divisor are successively set up on the keys of the disk 72, and the quotient can be read off on the quotient-register.

Although the different movements for each calculating operation in the machine 70 have been previously stated it may be convenient, in order to get a clearer view of the whole, to show how they combine together. In the above example of addition for instance, when the crank is turned one revolution clockwise the following takes place. 75

During the first quarter of the revolution of the crank:

The calculators 33 which represent tens, protruded from the calculating-rings, pass 80 the wheels 74, and the oblique teeth 36 on the calculators turn the said wheels, and the contact-wheels in gear with them, causing the wheels to advance as many teeth as corresponds to the number of oblique teeth 85 on the calculators. Those of the said wheels which are now brought into gear, on account of depressed keys, with their corresponding transmitting wheels, transmit movement to the result registering-wheels. 90 If the latter are not at zero, *i. e.*, if a number has previously been set upon the key board to which the number last transferred is to be added, and assuming that a result registering-wheel for example stands at 8, 95 and 4 is to be added so that carrying must take place, the hook 122 on the pin 124 engages the respective result registering-wheel when the sector 115 is moved one step clockwise and remains in that position. During 100 the latter part of the first quarter revolution the tooth 150 on the lever 148 has been brought into gear with the helical groove 108 on the cylinder 101.

At the beginning of the second quarter 105 revolution:

Firstly the roller 171 has been brought outward by the raised projection 168 (Fig. 9) so that the carriage has been inclined forward, through which the result registering-wheels 97 and the quotient registering-wheels 79 have been liberated from the wheels driving them.

Secondly the point 145 on the edge of the disk 132 has passed the roller 105, so 115 that the latter and the arm 106 are pressed downward, the consequence of which is that the sector 103 is brought upward causing the cylinder 101 to revolve. During this rotation the lever-arms 112 cause the sectors 120 115, through the bulges 110 on the parallel grooves 109, to be successively brought under the result registering-wheels 97 at the same time as the projections 111 on the cylinder 101 operate the springs 131, so that 125 the wheels 127 and 126 are made to turn, and the projection 129 operates the projections 116 on the sectors 115 so that the

latter are brought back to their first position; then the carrying (transference of ten) is performed.

Meanwhile, and until the point 144 has passed the roller 105, the carriage in consequence of the tooth 150 engaging the groove 108, has been moved up one pitch of the thread to the left, so that the result registering-wheels 97 have been brought into gear with the next transmitting-wheel to the left.

Toward the end of this stage in the calculation the raised projection 168 has passed the roller 171, whereby the carriage has been returned and the result registering-wheels 97 engaged with the transmitting-wheels 14, and one of the quotient registering-wheels 79 with the toothed wheel 77 (Fig. 8). At the same time the movement of the carriage has stopped. At this moment the protruded calculator of the ring 47 has reached the wheel 75 and has made this wheel and the wheels 77, 264, 265, 272, 273, turn one step, whereby, firstly a quotient registering-wheel, and secondly the type-wheel 275 farthest to the left in the printing mechanism, are turned one step and the figure 1 is brought forward both in the quotient register and at the left side of the printing mechanism.

At the end of this stage the course 143—142 has passed the roller 105 while the sector 103 has returned to its position of rest, and the spring 107 has turned the cylinder 101 back a revolution.

During the third quarter of the revolution the calculators projecting from the calculating cylinder and representing the units, pass the wheels 74, whereupon these wheels turn the contact wheels 12 and those of the latter, which by the depressing of the keys in the key-board, are in gear with the transmitting-wheels 14, turn said wheels 14 for the distance of as many teeth as correspond to the number of oblique teeth on the calculators pushed out. The result registering-wheels 97 are similarly turned a corresponding number of teeth. As stated above, the carriage has then moved a step to the left, on account of which the units do not come on the same wheel that has previously taken tens from a certain transmitting wheel, but on the nearest result registering-wheel to the left.

During the fourth quarter of the revolution the machine works similarly as during the second quarter revolution with the exception that the wheel 75 is not operated upon, since only one calculator is pushed out on the calculating-ring 47, and thus the quotient register remains unchanged during this operation. During this last period the end of the lever 148 passes the outer side of the raised projection 153 (Fig. 11), on account of which the tooth 150 is again brought into gear with the groove 108 so that the

cylinder 101, revolving back at the end of this period, moves the movable part of the carriage one step backward. At the end of this period the roller 302 on the lever 301 is also brought down through the opening 320 (Fig. 25), at which printing takes place in the above described manner.

The machine described above is only regarded as a suitable form of construction of the machine according to the present invention, and therefore a great number of detail arrangements may be altered without exceeding the bounds of the invention.

Thus, for instance, the printing mechanism can be altogether dispensed with, which may be the case in most of the machines adapted for ordinary practical purposes. Neither is it necessary to use a calculating mechanism in the form of the calculating-cylinder described, although such an arrangement is the most suitable when it is a question of reducing the size of the machine as much as possible. However, the invention includes, as stated above, every calculating arrangement which during positive calculating with work in the positive direction can combine work in the negative direction for the purpose of reducing the work in the machine to a minimum.

Instead of the indicated arrangement with keys and springs for manipulating the disk 72 much simpler arrangements can be used, thus both the keys and the springs 198 and 199 can be removed and the manipulation done by hand. In this case the disk 72 is provided with grooving on its edge and with an index coöperating with a numbered scale on the disk 71 or vice versa.

Previously steel-bands have been mentioned for effecting the various drives. It is evident, however, that other arrangements can be used, such as chains and chain-wheels, friction disks, or the like.

Finally, the above mentioned groove and cam disk with courses formed in them can be replaced by mechanical equivalents.

I claim as my invention:—

1. In a calculating machine, the combination of pairs of associated calculators, one calculator in each pair having teeth to represent tens, the other calculator having teeth to represent units, the number and positive or negative direction of operation of the teeth in each pair of calculators being such that, when the units digit of a partial product exceeds 5, the number in the tens teeth is one in excess of the tens digit of said product and the units teeth are of negative operation and complementary in number to the units digit in question, while when the unit figure of a product is 5 or less, the numbers of both tens and units teeth in the corresponding pair of calculators are equivalent to the digits of the product and the teeth are adapted to operate in positive direction; 130

and storing means forming an operative part of the counting gear for coöperating with said teeth and storing the said products.

2. In a calculating machine, the combination of pairs of associated calculators, one calculator in each pair having teeth to represent tens, the other calculator having teeth to represent units, the number and positive or negative direction of operation of the teeth in each pair of calculators being such that, when the units digit of a partial product exceeds 5, the number in the tens teeth is one in excess of the tens digit of said product and the units teeth are of negative operation and complementary in number to the units digit in question, while when the unit figure of a product is 5 or less, the numbers of both tens and units teeth in the corresponding pair of calculators are equivalent to the digits of the product and the teeth are adapted to operate in positive direction; and storing means forming an operative part of the counting gear for coöperating with said teeth and storing the said products in the operations of multiplying, dividing, addition and subtraction.

3. In a calculating machine, the combination of pairs of associated segmental calculators having their peripheries provided with obliquely inclined teeth some inclined in one direction to give a positive operation and others inclined in the opposite direction to give a negative operation, the teeth of one calculator representing tens and the teeth of the other associated calculator representing units, the number and positive or negative inclination and operation of the teeth in each of said pairs being such that, when the units digit of a partial product exceeds 5, the number in the tens teeth is one in excess of the tens digit of said product and the units teeth are of negative operation and complementary in number to the units digit in question, while when the unit figure of a product is 5 or less, the numbers of both tens and units teeth in the corresponding pair of calculators are equivalent to the digits of the product and the teeth are adapted to operate in positive direction; and storing means forming an operative part of the counting gear for coöperating with said teeth and storing the said products.

4. In a calculating machine, the combination of pairs of associated segmental calculators having their peripheries provided with obliquely inclined teeth some inclined in one direction to give a positive operation and others inclined in the opposite direction to give a negative operation, the teeth of one calculator representing tens and the teeth of the other associated calculator representing units, the number and positive or negative inclination and operation of the teeth in each of said pairs being such, that when the units digit of a partial product exceeds 5,

the number in the tens teeth is one in excess of the tens digit of said product and the units teeth are of negative operation and complementary in number to the units digit in question, while when the unit figure of a product is 5 or less, the numbers of both tens and units teeth in the corresponding pair of calculators are equivalent to the digits of the product and the teeth are adapted to operate in positive direction; and storing means forming an operative part of the counting gear for coöperating with said teeth and storing the said products, the said pairs of calculators moving in the same direction when carrying out positive and negative calculations.

5. In a calculating machine, the combination of pairs of associated calculators, one calculator in each pair having teeth to represent tens, the other calculator having teeth to represent units, the number and positive or negative direction of operation of the teeth in each pair of calculators being such that, when the units digit of a partial product exceeds 5, the number in the tens teeth is one in excess of the tens digit of said product and the units teeth are of negative operation and complementary in number to the units digit in question, while when the unit figure of a product is 5 or less, the numbers of both tens and units teeth in the corresponding pair of calculators are equivalent to the digits of the product and the teeth are adapted to operate in positive direction; and storing means forming an operative part of the counting gear for coöperating with said teeth and storing the said products in the operations of multiplying, dividing, addition and subtraction.

6. In a calculating machine, the combination of a rotatably mounted cylinder comprising nine calculating rings comprising ten pairs of calculator segments radially movable in the cylinders; obliquely inclined peripheral teeth on said segments some inclined in one direction and some inclined in the opposite direction; means for selectively projecting said pairs; means for rotating the cylinder; and storing means coöperating with said teeth.

7. In a calculating machine, the combination of a rotatably mounted cylinder comprising nine calculating rings comprising ten pairs of calculator segments radially movable in the cylinders, each pair of calculators being the ones diametrically opposite to each other; obliquely inclined peripheral teeth on said segments some inclined in one direction and some inclined in the opposite direction; means for selectively projecting said pairs; means for rotating the cylinder; and storing means coöperating with said teeth.

8. In a calculating machine, the combination of a rotatably mounted cylinder com-

prising end plates; distance plates between the end plates; rods passing through and connecting said plates; toothed-calculator segments mounted between the plates and 5 having shanks slideable between the rods; rollers in the inner ends of the segments; arms selectively revoluble about the axis of the cylinder and adapted to engage the rollers and protrude the segments thereof; and 10 storing mechanism adapted to be engaged by the teeth of the segments.

9. In a calculating machine, the combination of a rotatably mounted cylinder comprising end plates; distance plates between 15 the end plates; rods passing through and connecting said plates; toothed-calculator segments mounted between the plates and having shanks slideable between the rods; rollers in the inner ends of the segments; 20 arms selectively revoluble about the axis of the cylinder and adapted to engage the rollers and protrude the segments thereof; storing mechanism adapted to be engaged by the teeth of the segments; rollers immediately disposed in said shanks; a band 25 passed about said last named rollers and contacting the inner face of certain of said rods, the length of said band being such that only one pair of segments may be protruded 30 at a time.

10. In a calculating machine, the combination of pairs of associated calculators, one calculator in each pair having teeth to represent tens, the other calculator having 35 teeth to represent units, the number and positive or negative direction of operation of the teeth in each pair of calculators being such that, when the units digit of a partial product exceeds 5, the number in the 40 tens teeth is one in excess of the tens digit of said product and the units teeth are of negative operation and complementary in number to the units digit in question, while when the unit figure of a product is 5 or 45 less, the numbers of both tens and units teeth in the corresponding pair of calculators are equivalent to the digits of the product and the teeth are adapted to operate in positive direction; storing means forming 50 an operative part of the counting gear for coöoperating with said teeth and storing the said products in the operations of multiplying, dividing, addition and subtraction; a separate calculating ring having toothed 55 segments; means for protruding said segments one at a time corresponding to the number represented by the protruded calculator segments; means operatively associated with the separate ring for recording 60 the number represented by the protruded segments thereof.

11. In a calculating machine, the combination of a rotatable cylinder having protrudable segments having inclined teeth and 65 adapted when in operation to be rotated in

either direction; storing means adapted to be engaged by said teeth; a separate ring connected to the cylinder and having diametrically opposite pairs of segments having oppositely inclined teeth; means for 70 protruding one segment only at a time of one pair only at a time; means causing said protruding means to protrude one or the other of said segments in accordance with the direction in which the cylinder is rotated; and a recording means engaged and 75 operated by said teeth.

12. In a calculating machine, the combination of a rotatable cylinder having rings comprising protrudable segments having inclined teeth; means for selectively protruding said segments; rotatable shafts each associated with one ring and provided with a toothed wheel adapted to be driven by the protruded segment only of such ring; registering wheels slideable on said shafts but constrained to rotate therewith; a totalizer; intermediate wheels with which said registering wheels may be slidden into engagement; and means for selectively sliding the 90 registering wheels.

13. In a calculating machine, the combination of a rotatable cylinder having rings comprising protrudable segments having inclined teeth; means for selectively protruding said segments; rotatable shafts each associated with one ring and provided with a toothed wheel adapted to be driven by the protruded segment only of such ring only; registering wheels slideable on said shafts but 100 constrained to rotate therewith; a totalizer; intermediate wheels with which said registering wheels may be slidden into engagement; means for selectively sliding the registering wheels; a separate ring connected 105 to the cylinder and having diametrically opposite pairs of segments having oppositely inclined teeth; means for protruding one segment only at a time of one pair only at a time; an additional shaft having a toothed 110 wheel adapted to be engaged by the teeth of the protruded segments of said separate ring; a series of quotient registering wheels to register the number of operations in addition and subtraction, the multiplier or the 115 divisor; and another wheel on said additional shaft and adapted to operate the quotient registering wheels.

14. In a calculating machine, the combination of a rotatable calculating cylinder 120 having selectively protrudable toothed calculator segments; toothed wheels adapted to be operatively connected to said segments; a result registering wheel adapted to be moved into or out of engagement with 125 said wheels; a carriage carrying said result registering wheels, said carriage comprising a part which can be tilted during calculating and a part stationary during calculating; said stationary part comprising a slid- 130

ing base bar and a standard thereon; a stationary standard; a telescopic rod mounted in said standards; said movable part comprising a rotatable carriage cylinder; means for rotating the carriage cylinder; and means operated thereby for controlling the tilting of the carriage.

15. In a calculating machine, the combination of a rotatable calculating cylinder having selectively protrudable toothed calculator segments; toothed wheels adapted to be operatively connected to said segments; result registering wheels adapted to be moved into or out of engagement with said wheels; a carriage carrying said result registering wheels, said carriage comprising a part which can be tilted during calculating and a part stationary during calculating; said stationary part comprising a sliding base bar and a standard thereon; a stationary standard; a telescopic rod mounted in said standards; said movable part comprising a rotatable carriage cylinder; means for rotating the carriage cylinder; and means operated thereby for controlling the tilting of the carriage; the means for rotating the carriage cylinder comprising a cam on the calculating cylinder; a sector rocked by said cam; and a flexible means wound around the carriage cylinder and connected to the sector.

16. In a calculating machine, the combination of a rotatable calculating cylinder having selectively protrudable toothed calculator segments; toothed wheels adapted to be operatively connected to said segments; result registering wheels adapted to be moved into or out of engagement with said wheels; a carriage carrying said result registering wheels, said carriage comprising a part which can be tilted during calculating and a part stationary during calculating; said stationary part comprising a sliding base bar and a standard thereon; a stationary standard; a telescopic rod mounted in said standards; said movable part comprising a rotatable carriage cylinder; means for rotating the carriage cylinder; means operated thereby for controlling the tilting of the carriage; the means for rotating the carriage cylinder comprising a cam on the calculating cylinder; a sector rocked by said cam; and a flexible means wound around the carriage cylinder and connected to the sector; and a spring or the like for restoring the cylinder.

17. In a calculating machine, the combination of a rotatable calculating cylinder having selectively protrudable toothed calculating segments; transmitting wheels adapted to be operatively connected to said segments; result registering wheels adapted to engage the transmitting wheels; a carriage carrying transmitting wheels; a carriage cylinder in said carriage and provided

with circular grooves having bulges therein arranged in a spiral line; means for rotating said carriage cylinder; carrying mechanism between the result registering wheels; and means engaging in said grooves for controlling the carrying mechanisms.

18. In a calculating machine, the combination of a rotatable calculating cylinder having selectively protrudable toothed calculating segments; transmitting wheels adapted to be operatively connected to said segments; result registering-wheels adapted to engage the transmitting wheels; a carriage carrying transmitting wheels; a carriage cylinder in said carriage and provided with circular grooves having bulges therein arranged in a spiral line; means for rotating said carriage cylinder; carrying mechanism between the result registering wheels; means engaging in said grooves for controlling the carrying mechanisms.

19. In a calculating machine, the combination of a rotatable calculating cylinder having selectively protrudable toothed calculating segments; transmitting wheels adapted to be operatively connected to said segments; result registering wheels adapted to engage the transmitting wheels; a carriage carrying transmitting wheels; a carriage cylinder in said carriage and provided with a spiral groove; means for rotating said carriage cylinder; a cam carried on the calculating cylinder; and a lever operated by said cam and having an end adapted to engage in said groove, whereby when the carriage cylinder is rotated and the lever engaged in the groove the carriage cylinder and with it the carriage will be axially moved and the result registering wheels displaced relatively to the transmitting wheels.

20. In a calculating machine, the combination of a tubular shaft; an inner shaft in said tubular shaft; means for rotatably mounting said shafts for independent and coördinate movement; a cylinder mounted co-axially with said shafts for independent movement therewith; toothed segments in said cylinder; arms mounted on the tubular shaft for pushing out said segments; calculating mechanism engaged by the segments; and means for operating the shafts and cylinder.

21. In a calculating machine, the combination of a tubular shaft; an inner shaft in said tubular shaft; means for rotatably mounting said shafts for independent and coördinate movement; a cylinder mounted co-axially with said shafts for independent movement therewith; toothed segments in said cylinder; arms mounted on the tubular shaft for pushing out said segments; transmitting wheels adapted to be operated by the segments; result registering wheels operated by the transmitting wheels; a carriage for the result registering wheels; a cam carried

on the inner shaft; means operated by the cam for operating said carriage; and means for adjusting the relative positions of the shafts.

5 22. In a calculating machine, the combination of a tubular shaft; an inner shaft in said tubular shaft; means for rotatably mounting said shafts for independent and coördinate movement; a cylinder mounted 10 co-axially with said shafts for independent movement therewith; toothed segments in said cylinder; arms mounted on the tubular shaft for pushing out said segments; calculating mechanism engaged by the segments; 15 means for operating the shafts and cylinder; means operatively connected to the inner shaft for verifying the modes of the calculation of the mechanism; and means for adjusting the relative position of the shafts 20 to effect said verifying.

23. In a calculating machine, the combination of a calculating cylinder and a pair of shafts all co-axial; toothed calculators on the cylinder; a handle connected to one of 25 the shafts; a cam connected to the other shaft; storing mechanism actuated by said calculators; means operated by the cam for verifying the mode of the storing of said mechanism; and means for adjusting the 30 relative position of the shafts.

24. In a calculating machine, the combination of a calculating cylinder and a pair of shafts all co-axial; toothed calculators on the cylinder; a handle connected to one of 35 the shafts; a cam connected to the other shaft; storing mechanism actuated by said calculators; means operated by the cam for verifying the mode of the storing of said mechanism; and a bar connected to the shaft 40 to which the handle is not connected and adjustably connected to the handle.

25. In a calculating machine, the combination of a calculating cylinder and a pair of shafts all co-axial; toothed calculators on 45 the cylinder; a handle connected to one of the shafts; a cam connected to the other shaft; storing mechanism actuated by said calculators; means operated by the cam for controlling the mode of the storing of said 50 mechanism; flanges connected to the outer shaft and the cylinder respectively, the latter provided with a depression; a series of keys carried by the flange connected to the

outer shaft and adapted to engage in said depression to lock said shaft to the cylinder; 55 arms carried by the outer shaft and adapted to protrude the calculators to cause them to operate the storing mechanism.

26. In a calculating machine, the combination of a calculating cylinder and a pair of shafts all co-axial; toothed calculators on the cylinder; a handle connected to one of the shafts; a cam connected to the other shaft; storing mechanism actuated by said calculators; means operated by the cam 60 for controlling the mode of the storing of said mechanism; flanges connected to the outer shaft and the cylinder respectively, the latter provided with a depression: a series of keys carried by the flange connected 65 to the outer shaft and adapted to engage in said depression to lock said shaft to the cylinder; arms carried by the outer shaft and adapted to protrude the calculators to cause them to operate the storing mechanism; and 70 spiral springs interposed between said flanges and adapted to rotate them to cause the depressed key to move into the depression.

27. In a calculating machine, the combination of a calculating cylinder and a pair of shafts all co-axial; toothed calculators on the cylinder; a handle connected to one of the shafts; a cam connected to the other shaft; storing mechanism actuated by said 80 calculators; means operated by the cam for controlling the mode of the storing of said mechanism: flanges connected to the outer shaft and the cylinder respectively, the latter provided with a depression; a series of 85 keys carried by the flange connected to the outer shaft and adapted to engage in said depression to lock said shaft to the cylinder; arms carried by the outer shaft and adapted to protrude the calculators to cause them to 90 operate the storing mechanism; and a band of limited length adapted to bear on said keys and having such a length that only one of the keys may be depressed at a time. 95

In witness whereof, I have hereunto 100 signed my name in the presence of two subscribing witnesses.

JOHN CHRISTER ENBERG.
